UNITED STATES PATENT OFFICE.

FRANK R. MCBERTY, OF NEW ROCHELLE, NEW YORK, ASSIGNEE TO WESTERN ELECTRIC COMPANY, OF NEW YORK, N. Y., A CORPORATION OF ILLINOIS.

TELEPHONE-EXCHANGE SYSTEM.

1,125,579.

Specification of Letters Patent. Patented Jan. 19, 1915.

Application filed March 1, 1911. Serial No. 611,630.

To all whom it may concern:

Be it known that I, FRANK R. MCBERTY, citizen of the United States, residing at New Rochelle, in the county of Westchester and State of New York, have invented a certain new and useful Improvement in Telephone-Exchange Systems, of which the following is in full, clear, concise, and exact description.

10 My invention relates to telephone exchange systems and contemplates in general an improved organization and arrangement of circuits and apparatus whereby the interconnection of telephone lines and trunk lines 15 may be controlled and accomplished speedily and with precision.

The object of my invention is to provide an improved and novel telephone exchange system wherein the interconnection of telephone lines and trunk lines is accomplished by means of mechanical switching apparatus, such switching apparatus acting under the control of a sender or selection controlling organism to accomplish the accurate 5 and expeditious establishment of a desired connection.

A further object of my invention is to provide in an exchange in which the interconnection of subscribers' lines is accomplished by mechanical switching apparatus under the control of an operator improved and novel means whereby the automatic line selection may be simply and easily controlled and whereby such controlling means 5 may be automatically associated and dissociated with the mechanical switching apparatus at the proper stages in the operation of the system.

My invention therefore contemplates a telephone exchange system in which the interconnection of telephone lines and trunk lines is accomplished through mechanical switching apparatus comprising improved arrangements of circuits and apparatus whereby all the necessary functions of a modern telephone exchange system may be performed in the most accurate, rapid and satisfactory manner. The specific showing of my invention herein involved discloses what is known as a semi-mechanical telephone exchange system in which the interconnection of lines and trunk lines is accomplished by mechanical switching apparatus under the control of an operator, but such system involves many improvements

which are in no way specific to semi-mechanical systems. It will therefore be understood that my invention is in no way confined to the specific system and arrangement shown herein except as limited by the 60 hereinafter appended claims.

The accompanying drawings which illustrate the preferred form of my invention show, moreover, various features which form no part of my present invention and 65 are not claimed in this application. These features are claimed in my applications for Letters Patent as follows: Serial No. 573,516, filed July 23, 1910, for automatic telephone exchange selectors (Case 191); Serial No. 516,769, filed September 8, 1909, for trunking system for telephone exchanges (Case 192); Serial No. 515,933, filed September 2, 1909, for selective controlling apparatus (Case 193); Serial No. 528,293, filed November 16, 1909, for telephone exchange systems (Case 194); Serial No. 531,369, filed December 4, 1909, for telephone exchange systems (Case 195); Serial No. 533,928, filed December 18, 1909, for busy test system for party 70 telephone lines (Case 196); Serial No. 573,517, filed July 23, 1910, for telephone exchange systems (Case 197); Serial No. 574,089, filed July 27, 1910, for telephone exchange systems (Case 198); Serial No. 588,840, filed October 24, 1910, for semi-automatic telephone exchange systems (Case 200); Serial No. 511,983, filed August 9, 1909, for telephone exchange systems (Case 177). 75

In the drawings, which comprise ten sheets, Figures 1 to 10 when placed together form a single diagram illustrating the circuits and apparatus involved in an automatic exchange system forming the preferred form of my invention; the lines which extend to the edge of each sheet being continued on the neighboring sheet. The proper arrangement of the sheets for viewing the system as a whole is made by placing Figs. 1, 7, 8, 9 and 10 side by side in the order named; by placing Fig. 6 above and Fig. 2 below Fig. 1; by placing Fig. 3 to the left of Fig. 2; and by placing Fig. 4 above and Fig. 5 below Fig. 3. 80

The same reference numerals indicate the same parts wherever they are shown.

Selectors.—A part of the apparatus involving the preferred form of my invention and as shown in the drawings herein com- 105 210

prises automatic selectors or mechanical switching devices such as are shown on Figs. 1, 7, 8 and 9.

In the form of automatic switch shown in Fig. 9, which is known as a final selector, the switch carriage or movable element is provided with a number of sets of multiple brushes, any particular set of which may be selected for service and the switch carriage 16 is then advanced over a series of sets of line terminals until the selected brushes are brought into engagement with the terminals of a desired line.

The switch carriage or brush carrying member is of the rotary type, the frame 21 of which is mounted upon a central standard or shaft 22. At the outer end of the frame a number of sets of contact brushes 23, 24, 25 are pivotally mounted upon but 20 insulated from a rod 26, and from each other, in position to sweep over sets of line terminals 27, 28, 29. The brushes have inwardly extending arms 30, bearing against which, one for each brush, are springs 31. 25 Latches 32 one for each set of three brushes, are pivotally mounted upon a rod 36 and arranged to normally hold the brushes from being rocked outwardly into line with the stationary terminals. Bearing against the 30 inner ends of the latches are springs 34 which hold the latches firmly against a stop rod 33. This stop rod 33 serves to prevent the latches from being moved forward too far after the brushes have been released. A 35 stop bar 35 serves to limit the outward movement of the brushes when the latches are withdrawn. The latches 32 and stop bar 35 are of insulating material so that the circuits connected with the brushes will 40 not be crossed thereby. The springs 31 make electrical connection with the brushes; they are of sheet metal and form the teeth of combs which connect corresponding brushes in the several sets in multiple. Suitable wire clip terminals 37, 38 and 39 are 45 provided for the circuit connections to the springs and brushes.

As the brush carriage is rotated to cause the brushes to sweep over the fixed terminals, the latches first pass by a tripping device or brush selector, by which any desired set of brushes may be released and caused to swing outwardly. This tripping device 50 comprises a shaft 40 provided with radially extending fingers 41 arranged spirally about the surface of the shaft. This shaft is adapted by mechanism, to be presently described, to be rotated so as to bring the fingers one after another into the line of travel of the several latches on the brush carriage. Only one set of brushes is intended to be released in a given operation. The shaft is first rotated to bring a particular finger into position to engage the latch in the same level 55 therewith and then the brush carriage is

rotated. In passing, the outward edge of this latch strikes the end of the finger, allowing one set of three brushes to be released. Continued movement of the brush carriage brings the selected set of brushes into engagement with the rows of stationary terminals in the same level therewith, these brushes trailing over the terminals and making contact therewith in passing. The brush carriage is finally caused to stop with 75 the selected brushes in contact with some one set of stationary terminals. The other brushes, not being released, are held out of contact with the terminals over which they pass. A further movement of the brush carriage in the same direction of rotation will carry the brushes over a restoring roller 69, which may be pivoted to the frame and which engages the free ends of the released set, causing them to be pushed back into 80 their normal latched position. After making a full revolution, the brush carriage is brought to rest in its normal position again.

The brush selector and the brush carriage of this switch mechanism are arranged to be moved one following the other by suitable motor mechanisms which will impart to each a continuous movement. In order that the successive positions taken by each movable member may be stepped off or measured, each is provided with an interrupter device 90 adapted to make and break a contact in the controlling circuit as the moving member passes the several positions at which it may be desired to cause said member to stop. This interrupter device for the brush carriage comprises a pair of contact springs 48, 49 secured to the shaft 22, but insulated from said shaft and from each other. The outer ends of these springs are engaged by inwardly extending arms 44 and 45 of a pair of levers 42, 43, which are pivotally mounted upon the rod 26. These levers 42 and 43 are insulated from the springs 48 and 49 by small insulating buttons at the ends of the arms 44 and 45, but are uninsulated from the rod 26 which is connected to ground through the frame of the selector mechanism. In the movement of the brush carriage a roller 51 on the free end of the lever 42 engages the teeth 53 of a cam plate 50, the roller engaging each tooth as the brushes are traversing the space between the successive terminals and dropping into the notches between the teeth as the brushes are centrally located in contact with said terminals. While the roller 51 is riding over the teeth of the plate 50 the curved end of the lever 43 is in engagement with the smooth edge 52' of that plate. A relative movement of the levers 42 and 43 is thus obtained by their engagement with the edges of plate 50 and this movement is, therefore, independent of slight variations in the radial distance between the plate and the axis 100 105 110 115 120 125 130

of movement of the brush carriage. By this construction the duration of contact between the interrupter springs 48 and 49 is made uniform in the movement of the brush carriage, each make and each break corresponding to a particular position of the brushes with respect to the terminals.

In the normal position of the switch mechanism, the levers 42 and 43 rest in a recess 47 of a normal stop plate 46. The entering edge 55 of this plate is covered with insulating material in order to prevent the free ends of the levers 42 and 43 from making electrical contact with the plate 46 before reaching the full normal position in which the ends of the levers drop into the recess 47.

The interrupter for the brush selector comprises an arm 56 pivoted to the frame at 57, engaging at its free end a toothed wheel or cam 58 which rotates with the shaft 40. This arm 56 is adapted on the rotation of the shaft to engage two contacts 59 and 60. These contacts may be springs, the free ends only of which are shown in the drawing. In its normal position the free end of the arm 56 lies in a notch of the cam 58 which is deep enough to insure an open connection with contact 59. When the shaft is away from its normal position, however, connection is made continuously with contact 59. The connection with contact 60 is intermittent, this contact being made when the arm 56 is lifted by each tooth of the cam. There are as many teeth on the cam as there are fingers 41 on the spindle 40 and therefore as many as there are sets of brushes.

The motor mechanism for causing rotation of the brush carriage comprises an annular iron friction disk 61 flexibly mounted at the lower end of the spindle 22, an electromagnet 62 which may be fixed in any suitable manner to the frame, and a constantly rotating shaft 63 carrying an iron driving roller 64. The disk 61, roller 64 and that part of the shaft 63 which extends through the center of the electromagnet 62 form the magnetic circuit of the electromagnet 62. When therefore current is passed through the winding of the magnet, the roller 64 attracts the disk 61 and causes the latter to rotate by frictional contact therewith. A holding electromagnet 65 having a pole piece 66 extending upwardly beneath the disk 61 is adapted when current is passed through its winding to engage the disk and hold it from movement. The power shaft 63 is extended as shown in the drawing to carry a flexibly mounted driving disk 70, which is adapted to engage a roller 67 carried by the spindle 40. An electromagnet 68 controls the engagement of disk 70 and roller 67 in the same manner that the electromagnet 62 controls the engagement of disk

61 and roller 64. These devices are in fact electromagnetic clutches, one to cause movement of the brush carriage and the other to cause movement of the brush selector.

The complete selector switch mechanism 70 is not shown in the drawing, but the elements thereof appear in their proper relation to one another so as to make clear the manner in which the mechanism operates to interconnect lines. There may be as many 75 sets of brushes and stationary terminals as desired. For example, the switch mechanism may, as a whole, have ten sets of three brushes each and two hundred sets of fixed terminals arranged in ten levels of twenty 80 sets each. For simplicity in the diagram there are shown only two sets of brushes, the 8th and 9th counting from the top down, and six sets of stationary terminals in two levels corresponding to the two sets of 85 brushes shown.

The structure of the automatic selectors or mechanical switching devices shown in Figs. 1, 7 and 8 is precisely similar to the structure shown in Fig. 9 and hereinbefore described; with the exception of the interrupter apparatus shown at the top of such structures, the structure and operation of which are as follows: In the normal position of the brush carriage, as shown in Fig. 1 for example, a pair of levers 42, 43 pivoted upon the rod 26, the latter being insulated therefrom, engage at their free ends a normal stop plate 46. At the end of lever 42 is a roller 71 which lies in a recess of plate 46, and at the end of lever 43 is a right angle extension arm 72 which makes electrical contact with said plate 46. A coil spring 54, acting upon an inwardly extending arm 44, serves to press the roller 71 with considerable force against plate 46 and thereby holds the brush carriage securely in its normal position. A flat spring 52 engages an inwardly extending arm 45 of the lever 43 and serves to press this lever outwardly but with less force than that of the coil spring 54. The spring 52 also makes electrical contact with lever 43: it is secured to but insulated from the shaft 22 of the brush carriage and terminates in a wire clip. 115

As the brush carriage is moved to carry the brushes over the stationary terminals, the roller 71 and the extension arm 72 engages the teeth of a cam plate 50. The roller 71 rides over the teeth while the brushes are passing between terminals and drops into a notch as any released set of brushes is centrally located in direct contact with a set of terminals. The extension arm 72 follows behind the roller one tooth or notch and likewise engages a tooth as the brushes are passing between successive terminals. It passes through the space between teeth, however, without touching the plate 50, as the released set of brushes is centrally located in 130

contact with the terminals. The stop bar 35 engages the inwardly extending arm 45 just as it does the arms 30 of the brushes and thus prevents the extension arm 72 of the 5 lever 43 from touching the bottom of the notches between the teeth of plate 50, but permitting said arm 72 to touch and make contact with the top of the teeth. The 10 teeth and notches of plate 50 are so spaced and arranged with respect to the contact lever 43 that the extension arm 72 will not break contact with a tooth of plate 50 until after the brushes make contact with the stationary terminals and the roller 71 is ready 15 to drop into a notch. The circuit arrangement, as will presently appear, is such that the motive power for driving the brush carriage cannot be cut off until the contact is thus broken between lever 43 and plate 50 20 and therefore not until the brushes are in position to make good contact with the stationary terminals.

Sequence switches.—The local controlling circuits associated with the various 25 parts of the exchange system disclosed herein, which local controlling circuits must be established in definite order at successive stages of the operation of such system to bring into service the different 30 devices or parts as they are required, are in the present embodiment of my invention established by automatic electromechanical switching appliances which are termed sequence switches. As will be noted by reference 35 to the drawing, there is a sequence switch associated with the operator's connecting circuit and the district selector switch, on Fig. 1 of the drawings; a sequence switch associated with the operator's listening-in apparatus on Fig. 6 of the drawings; a sequence switch associated with the cord finder apparatus on Fig. 2 of the drawings; a sequence switch associated with the sender apparatus on Fig. 3 of the drawings; 40 a sequence switch associated with the office selector switch on Fig. 7 of the drawings; a sequence switch associated with the group selector switch on Fig. 8 of the drawings; and finally a sequence switch associated with the final selector switch on Fig. 50 9 of the drawings. Each of these sequence switches consists in its elements of a movable switch operating member, a number of circuit changers or contact devices adapted 55 to be actuated in sequence as said member is moved from one position to another, an electromagnet, and a motor mechanism operated and controlled by said magnet for advancing said movable member through 60 its successive positions.

The sequence switch may control any desired sequence of operations whether of the same or of different devices. In each position to which this movable member is advanced, a circuit is established whereby a 65

given operation of the device or devices under control is made possible, and at the same time another circuit is established whereby the motor mechanism of the sequence switch may be actuated automatically when such operation of the device or devices under control has been completed: so that as each operation takes place the sequence switch will be automatically moved to the next position, in which position a new operation or another stage of the same operation will be brought about and so on. Finally the sequence switch establishes a condition whereby the apparatus under control is returned to its normal condition, and also establishes a circuit whereby the sequence switch will be returned to its normal position. In each such position of the sequence switch, the apparatus and its associated sequence switch may be and are preferably so related that local reciprocal controlling circuits will be progressively established by said devices in their operation in such a manner that when a normal operation of either is started, both devices will be progressively carried through a complete cycle of operations which may be controlled and checked at different stages through the agency of energizing circuits established by some other portion of the apparatus for this purpose, but which unless so checked will terminate in the automatic return of both the sequence switch and its associated apparatus to normal condition. In case of a failure of current in such checking or controlling circuit, even if such failure occurs immediately after a sequence switch and its associated apparatus have started in operation, such sequence switch and apparatus cannot become permanently displaced or stalled in an off-normal condition, but will complete their cycle of operations and be positively returned to normal under control of circuits which are purely local.

In the circuit diagram herein illustrating my invention, the switch springs of the sequence switches are not shown in their actual arrangement with relation to each other or to the movable or commutating member, but are so located upon the drawings as to give the clearest arrangement of circuits. Furthermore, the operating cams are not shown. The positions of the rotary element or commutating member of each sequence switch in which any of its contacts are closed, are indicated by numbers placed adjacent to such contacts, each contact, except the special contact which will be hereinafter referred to, being open in all positions except those indicated by the adjacent members. It may be here noted that all of the sequence switch contacts shown on Fig. 1 of the drawings form a part of the sequence switch indicated diagrammatically

thereon at 101; that on Fig. 2 all of the sequence switch contacts, the hundreds digit of whose reference character is 2, form a part of the sequence switch shown thereon at 222, with the exception of the sequence switch contacts 275 and 224; that on Fig. 2 all of the sequence switch contacts, the hundreds digit of whose reference character is 3, and also the sequence switch contacts, 10 the hundreds digit of whose reference character is 3 on Fig. 5, form a part of the sequence switch shown on Fig. 2 at 336; that all of the sequence switch contacts shown on Fig. 6 form part of the sequence switch shown thereon at 176; that all of the sequence switch contacts shown on Fig. 7 15 form a part of the sequence switch shown thereon at 801; that all of the sequence switch contacts shown on Fig. 8 form a part of the sequence switch shown thereon at 851; and that all of the sequence switch contacts shown on Fig. 9 form a part of the sequence switch shown thereon at 901.

Each sequence switch has, however, as has been before noted, a special contact, governing the local circuit of its motor magnet. These special contacts, which are shown immediately adjacent to the diagrammatic showing of the sequence switch motor magnet, as, for example, will appear on Fig. 1, the special contact being contact 102 associated with the sequence switch 101, are closed only while the rotary element of the sequence switch is in transit from one stopping position to the next. For this reason the numbers indicating its condition are placed on the side of the switch lever opposite from the contact and indicate the positions in which such contact is open, such 20 contact being closed at all times while the rotary element or commutating member is in transit between the positions indicated by such numbers. The numbers adjacent to these special contacts of the various sequence switches indicate therefore the only positions in which their associated sequence switches are arranged to stop.

Since, however, sequence switches of the character indicated are well known in the art, the particular structure and arrangement of the form used and shown in the preferred embodiment of my invention need not be particularly described herein and any form thereof which may be suitable or convenient may be used.

Cord finder.—The cord finder forming a part of the embodiment of my invention herein shown may be of any suitable construction and arrangement, but preferably 0 involves a set of brushes adapted to sweep 5 over the terminals leading to the various connecting circuits and to stop with its brushes in contact with the terminals leading to the connecting circuit over which it is desired to interconnect a desired line with

the calling line. The structure of this cord finder may be of any suitable design and the particular structure forms no essential part of my invention. The mechanism shown, however, comprises five brushes 230, 231, 232, 233 and 234 and as many sets of five stationary terminals, such as 235, 236, 237, 238 and 239 as there are connecting circuits in an operator's position. The brushes are mounted on a carriage adapted to rotate upon a shaft at the lower end of which is flexibly mounted the usual friction driving disk similar to that shown in the selector switches herein before described. This mechanism also includes the motor 80 mechanism comprising the constantly rotating power shaft, the power magnet and the holding magnet, all adapted to cooperate with the flexibly mounted disk to drive the same and the brushes associated therewith until connection is made with the terminals of the cord circuit taken for use and then to hold them in such position precisely as do the power and holding apparatus of the selector switches hereinbefore described. The mode of control of the brush carriage of this cord finder is substantially the same as that of the selector brush carriage and a test relay 229 controls the circuit of said magnets in a manner similar to the mode of control of the corresponding magnets of the selector switch. The operation of the cord finder will sufficiently appear from the description of the operation of my invention as a whole.

Keys and registers.—The various circuits which determine the selection controlling operations of the operator's sender or controlling equipment shown herein are established by a plurality of recording devices, 105 herein termed registers, which take their positions in response to the operation of manually operable keys controlled by an operator, upon which the designation of the line desired may be indicated. In systems 110 of the character in which my invention is designed to be used some of the lines and trunks, or the lines and trunks at some of the exchanges, may be grouped or classified upon a non-decimal basis and in order to 115 control the proper selection of a line or trunk where such line or trunk is grouped or classified upon a non-decimal basis, "translation" is required in order that the number keys, which are usually arranged 120 according to the decimal system, may cause operations of the sender proper, in the embodiment shown a set of so-called "counting relays," to control the selection according to the non-decimal grouping of lines 125 and trunks in an exchange. In the equipment shown, where such translation is necessary or desirable, it is accomplished by the registers referred to, which are in this instance adapted to take positions in re- 130

sponse to the depression of keys representing a number according to the decimal system, and in such position to control selecting operations according to a non-decimal system, such selection controlling operations governing a selection according to such translated system of the number designated by the keys. When, however, the line desired is to be found in an exchange in which 10 the grouping of lines and trunks is upon the decimal system the registers will take positions in response to the depression of the keys representing the number according to the decimal system, and will in turn 15 produce selection controlling operations according to the decimal system of notation. As will be hereinafter pointed out, whether this control will involve translation or not will depend upon the office key depressed 20 and will not require any additional or further act by the operator than the depression of the keys indicating the designation of the line desired.

The registers which are associated with 25 the counting relays also serve to record or store up designations indicated by any combination of depressed keys, and thereby establish permanent conditions for governing the conditions of selection controlling operations required to cause the selection of 30 the desired line, so that when the call is thus registered or stored up upon one sender apparatus the set of keys may be used thereafter to register another call upon another 35 sender apparatus before the first sender apparatus has finished the selection controlling operations of the first call. There may be, and is preferably, one key for each office or exchange of the system, and also a bank 40 of number keys, which, as diagrammatically indicated, comprise four rows of ten keys each, representing the figures 0 to 9, inclusive, of thousands, hundreds, tens and units digits respectively. These keys, both 45 the office and number keys, are designed to be held in their depressed position by the locking magnets 422 indicated upon the drawing, the locking magnet associated with any one set of keys being adapted to 50 retain in its depressed position the depressed key of said set of keys until such locking magnet is deenergized. Upon the deenergization of the locking magnet associated with any set of keys the depressed 55 key will be restored to its normal position by means not shown, but which are usual in apparatus of this character. Each key when depressed is adapted to close certain contacts governing circuits which are shown 60 in the diagram and which will be herein-after traced in detail.

The preferred form of the registers, such as are used in connection with my invention and shown diagrammatically in Fig. 3, is

the same as that of the sequence switches 65 hereinbefore referred to and described, with the addition of a stop relay. These registers are shown each as embodying the usual power magnet, a stop relay and a plurality of sets of contact devices. The sets of contact devices shown above the power magnet and stop relay are those connected to the operators' keys and by which is determined the position in which the register will stop, and the sets of contact devices located below 70 the power magnet and stop relay upon Figs. 3 and 5 are the ones closed in the various positions of the register to determine the operation of the sender proper. The registers, as do the sequence switches, involve a 80 special contact which in the registers is open in each of the positions of the register but closed between each two positions thereof. This special contact is shown immediately to the left of the associated power magnet. 85 As in the ordinary sequence switches, the contact devices of the registers are open in all the positions except those indicated upon the drawings immediately adjacent the contact devices. It will be noted, however, that 90 the positions of the registers range from zero to nine and that there is no normal position of the register, the register remaining, after it has performed its function, in the position in which it was set, and when 95 next taken for use in connection with the operators' keys, it starts from such position.

As shown in the circuit diagram, each sender device proper forming a part of my invention may have, and preferably does 100 have, six registers associated therewith, corresponding respectively to the districts of the system, the office in a district, and the thousands, the hundreds, the tens and the units of the designation of the line desired. 105

As will be hereinafter described, when the registers are brought successively into association with the sender or selection controlling apparatus proper, herein shown as counting relays, the contact devices shown 110 below the power magnets of the respective registers will control the operation of such counting relays to accomplish the selection controlling operation desired. Thus when the tens key 427 is depressed, for example, 115 it causes the tens register to take up its sixth or No. 5 position, thereby closing the contact device 608, which at the proper time will ground conductor 725 leading to the counting relays to control the action of such 120 relays, which relays in turn govern the selection controlling operation of the sender as a whole. It will be noted that both the district and office registers respond to the depression of a single key of the set of office 125 keys, whereas the other registers of the group are individual to the corresponding sets of keys. It will, therefore, be apparent

that the district and office registers will respond to the depression of an office key to record the district in which such office is located and which particular office in such district the office corresponding to the depressed key is. The numerical registers similarly will respond to the depression of the numerical keys to take up positions corresponding to the depressed keys in their respectively associated set of keys. In each position the cams of the registers will close a certain distinctive combination of switch contacts, whereby the operation of the counting relays may be controlled.

Counting relays.—In the form of my invention shown herein a part of the sender or selection controlling apparatus comprises a set of counting relays which in fact may be called the sender proper. These counting relays, which in the particular embodiment of my invention disclosed herein are arranged in two groups of twenty relays each, serve directly to control the selecting operations of the various selector switches which are taken for use in the course of establishing the desired connection. The relays themselves are of any preferred or suitable construction. The arrangement and operation of these counting relays will sufficiently appear in the description of the operation of the system as a whole.

General description and operation.—Taking up now the operation of the system as a whole, it will be observed first that the exchange shown in detail in the drawings herewith is assumed to have a capacity of 500 subscribers' lines, which lines are arranged in two groups of 200 each upon two groups of final selectors such as shown on Fig. 9, and a third group of but 100 lines upon a third group of such final selectors. These final switches are each designed to accommodate 200 lines as noted and have ten banks of sets of contact terminals, each bank upon the first two groups of final selectors referred to comprising 20 of such sets. The numerical arrangement of these sets of terminals will be referred to hereinafter. To reach these final selectors, such as shown on Fig. 9, a calling line is first connected with a district selector such as shown on Fig. 1. This district selector in the embodiment of my invention shown herein will select and find an idle trunk leading to a particular group out of ten groups of office selectors. When connection has been made by this district selector between the calling line and an idle office selector, the office selector will in turn select and make connection with an idle trunk line leading to the particular office desired; that is to say, the office in which the particular desired line terminates. The calling line having been connected by the office selector with the trunk

line leading to the desired office and to the 65 group selector in which this trunk line terminates, this group selector now selects and makes connection with an idle final selector of the particular group in which the line desired appears.

It will be obvious that, by a proper arrangement and construction of selector switches, exchanges embodying my invention may be of any desired capacity and such exchanges of various size are within the 75 contemplation of my invention, the exchange of the particular size shown being used as an example for convenience and clearness in demonstrating the various features of my invention.

Assuming that the subscriber whose line and substation apparatus is shown in the extreme left of Fig. 1 desires connection with some other subscriber of the system, for example, No. 354 of the exchange shown 80 in detail herein, which exchange is exchange No. 4 of the system, he will first remove his receiver from its hook 92, thereby closing in the usual manner a circuit for his line relay 82, causing the lighting of the line lamp 85 83. The operator upon receiving this signal will insert the plug 141 of an idle connecting circuit into the jack 81 individual to the subscriber's line. A circuit will now be established from the middle point of the battery 99 through the cord relay 142, sleeve contact of the plug 141, sleeve contact of the jack 81, cutoff relay 84 of the subscriber's line to ground and back to battery. The closure of this circuit causes the energization 90 95 of the cord relay 142, and the cutoff relay 84, the cutoff relay opening the normal connection from the subscriber's line to ground and to battery and causing the deenergization of the line relay 82 and the 100 105 consequent extinguishment of the line lamp 82, as is usual and well understood.

The insertion of the plug 141 in the jack of the calling subscriber has also energized the supervisory relay 145 over a circuit 110 which also serves as the talking battery supply circuit of the calling subscriber. This circuit may be traced from the battery 100 through the upper portion of the left winding of the repeating coil 154, listening 115 sequence switch contact 180, tip contact of the plug 141, tip spring of the jack 81, out over one side of the calling subscriber's line, through his transmitter, the switch hook 92, primary winding of his induction 120 coil, back over the other side of his line through the ring spring of the jack 81, ring contact of the plug 141, supervisory relay 145, listening sequence switch contact 181, lower winding of the left winding of the repeating coil 154 and back to battery. The energization 125 of the supervisory relay 145 at this time is to prevent the lighting of the super-

visory signal 156 when the district sequence switch comes into its third position except under control of the calling subscriber, for purposes which will be hereinafter described.

5 Upon the attraction of the armature 144 of the cord relay 142 a circuit was established from battery through the listening sequence switch 176, listening sequence switch contact 178, front contact and armature 144 of the cord relay 142 to ground and back to battery. This energizes the listening sequence switch 176 and it moves from its first position, in this movement opening the 10 sequence switch contact 178 and also the sequence switch contact 179. The listening sequence switch will now move under control of its special contact 177 into its fifth position. On coming into its second position, 15 it closed and will maintain closed in its fifth position a circuit from battery through the district sequence switch 101, district sequence switch contact 103, listening sequence switch contact 183, front contact and armature 144 of the cord relay 142 to ground and back to battery. This causes the energization 20 of the district sequence switch which moves into its second position.

Before investigating what occurs in the 25 district selector apparatus as a result of this movement of the district sequence switch, it will be observed that when the listening sequence switch left its fourth position, it opened the sequence switch contacts 180 and 181, closing, however, before these contacts were opened, the coöperating contacts 184 and 185 and also maintaining these contacts closed in its fifth position. It will be furthermore observed that on coming into 30 the fourth position, it closed the sequence switch contacts 186 and 187 and on coming into the fifth position it closed the sequence switch contacts 188, 189 and 190. In the fifth position consequently the operator's 35 telephone set indicated at 192 will be bridged across the talking strands of the cord circuit and in conversational connection with the calling subscriber, such circuit being traced from the operator's set 192 through the normal contact of the upper 40 spring of the key 193, sequence switch contact 184, tip strand of the cord circuit, tip contact of the plug 141, tip spring of the subscriber's jack 81 and out over one side 45 of his line to the substation, back over the other side of the line through the ring spring of the jack 81, ring contact of the plug 141, ring strand of the cord circuit including the supervisory relay 145, sequence 50 switch contact 185, normal contact of the lower spring of the key 193 and back to the operator's telephone set. The operator will now learn from the calling subscriber the designation of the desired line.

55 In the meanwhile, however, the movement

of the district sequence switch into its second position has closed a circuit from battery (see Fig. 2) through the cord finder sequence switch 222 of the first idle cord finder, which for the present it will be assumed is the first cord finder associated with this operator's position, through the sequence switch contact 202, through the sequence switch contact 275 of the sequence switch 272 of the second cord finder of this operator's position, common conductor 111, district sequence switch contact 108, back contact and armature 147 of the restoring relay 146 to ground and back to battery. The establishment of this circuit energizes the cord finder sequence switch 222 which moves into its second position. It will also be observed that the district sequence switch on coming into its second position has closed various other sequence switch contacts for purposes which will hereinafter appear.

The cord finder sequence switch on coming into its second position has established a circuit for the power magnet 226 from battery through such power magnet, sequence switch contact 205, back contact and armature 228 of the test relay 229 to ground and back to battery. The closure of this circuit energizes the power magnet 226 and the brush carriage 227 begins to rotate. When the brushes 230, 231, 232, 233 and 234 come in contact with the terminals 235, 236, 237, 238, 239 individual to the cord circuit which has been taken for use, a circuit is established from battery through the test relay 229, sequence switch contact 203, brush 230 of the cord finder, contact terminal 235, conductor 112, district sequence switch contact 109, back contact and armature 147 of the restoring relay 146 to ground and back to battery. The closure of this circuit causes the energization of the test relay 229 which, by the attraction of its armature 228 opens the circuit for the power magnet 226, and at the same time closes the circuit of the holding magnet 242 through the sequence switch contact 207 and the front contact of the armature 228, so that the brush carriage will be stopped and held with the brushes carried thereby in proper contact with the contact terminals of the cord circuit taken for use.

A circuit is also closed by the energization of the test relay 229 through the sequence switch contact 217 for driving the cord finder sequence switch 222 out of its second position, and this sequence switch thereupon moves under control of the special contact 201 into its fifth position. As the cord finder sequence switch comes into its fourth position, it closes and maintains closed in its fifth position a circuit from battery through the test relay 229, sequence switch contact 204, reset relay 332, sender sequence switch contact 304, conductor 245,

brush 232 upon the cord finder contact terminal 237, conductor 115, district sequence switch contact 110, back contact and armature 147 of the restoring relay 146 to ground 5 and back to battery. The closure of this circuit provides a new energizing path for the test relay 229 and energizes the reset relay 332. The energization of the reset relay 332 has caused it to attract its armatures 333 10 and 334, the armature 333 providing for the reset relay 332 a substitute energizing path around the sequence switch contact 304 which will be opened as soon as the sender sequence switch moves out of its first position, which movement takes place at this 15 time due to the closure of a circuit for said sender sequence switch 336 through the front contact and armature 334 of the reset relay 332 and the sender sequence switch contact 302. The circuit now established for the test relay 229 and the reset relay 332 will be maintained and these relays kept energized from this time on so long as the cord finder and the sender are required in connection 20 with the establishment of the desired connection. As will be hereinafter pointed out, the deenergization of these two relays at this time or any time hereafter will cause the immediate return of the entire cord finder 25 and sender apparatus to their normal position.

The apparatus which we have so far considered is now in condition for the depression by the operator of the various keys 30 shown on Fig. 4 indicating the designation of the desired line, the district sequence switch being in its second position, the listening sequence switch in its fifth position, the cord finder sequence switch in its fifth 35 position and the sender sequence switch in its second position. It will be noted furthermore that the movement of the cord finder and sender sequence switches has taken place rapidly and while the operator 40 has been learning from the subscriber the designation of the desired line. After the operator has once been informed by the subscriber with what line connection is desired, the listening switch may be moved out of its 45 fifth and into its eighth position to cut out the operator's telephone set without in any way affecting the operations taking place in the other apparatus shown. This arrangement makes it possible for the operator— 50 having learned the designation of the desired line and having depressed the keys corresponding to such designation—to go on with her work without waiting for the various selection controlling operations to take 55 place. Therefore when the plug of a second cord is placed in the jack of a calling subscriber, the movement of its listening sequence switch from its first to its fifth position, as has been hereinbefore described 60 in connection with the sequence switch 176,

will close its sequence switch contact 195 corresponding to the sequence switch contact 182 of the listening sequence switch 176, thereby placing a ground upon the common conductor and closing an energizing circuit 70 for the first listening sequence switch 176 through the sequence switch contact 190. This causes the listening sequence switch 176 to move out of its fifth position and continue moving under the influence of its special contact 177 into its eighth position. This movement of the listening sequence switch 176 has entirely disconnected the operator's telephone set 192 from the first cord circuit by opening the sequence switch contacts 184, 185, 186 and 187. This same movement of the listening sequence switch has completed again the talking strands of the cord circuit by closing the sequence switch contacts 180 and 181. The listening 75 sequence switch 176 will now stay in its eighth position until by the removal of the plug 141 from the jack 81 upon disconnection a circuit is completed for the listening sequence switch through the sequence switch contact 181 and the back contact and armature 144 of the cord relay 142, or until some time prior to disconnection the operator desires to again place herself in conversational connection with the calling or 80 called party, at which time she will depress her listening-in key 197, thereby closing an energizing circuit for the listening sequence switch through the sequence switch contact 175. It will be observed that upon disconnection the circuit for moving the listening sequence switch out of its eighth position will move it into its first position and it will there come to rest, the sequence switch contact 191 being open in the first position 100 of the listening sequence switch and no ground connection now being completed over the sequence switch contact 178. When, however, prior to disconnection the operator depresses her listening-in key 197, 110 the listening sequence switch will not stop in its first position, but will continue to move into its fifth position when the operator's telephone set 192 will be again bridged across the talking strands of the associated 115 cord circuit. This movement is accomplished by the circuit through the sequence switch contact 175 and the listening-in key 197 which drives the listening sequence switch from its eighth into its first position 120 and by the circuit including the sequence switch contact 178 and the front contact and armature 144 of the cord relay 142 which drives the listening sequence switch from its first position, it moving into its fifth position 125 under the influence of its special contact 177.

The listening-in key 197 it should be noted is individual to the cord circuit with which it is associated, but the master wipe 130

out key 199, the master listening-out key 198 and the master flash back key 196, the function of which keys will be hereinafter described, are common to an operator's position and are associated with a particular cord only when the listening sequence switch of such cord is in the listening or fifth position. It may also be noted that so long as the key 193 remains in its normal position, the continuity of the talking strands of the cord circuit is maintained in all positions of the listening sequence switch either directly through the sequence switch contacts 180, 181, or through the contacts 15 of the key 193. At all times, therefore, while the plug 141 is in the jack 81 of the calling subscriber, he will be supplied with talking current from the battery 100 through the talking strands of the cord circuit and the tip and ring contacts of the plug 141.

The operator having learned that the calling subscriber desires connection with a particular line, in this instance as assumed line 25 No. 354 of exchange No. 4 of the system, and the various sequence switches having come into the positions hereinbefore noted awaiting the depression of the keys, it now only remains for the operator to depress the 30 keys according to the line designation assumed in order to produce the necessary selection controlling operations. It may here be noted that the operations of the district cord finder and sender sequence 35 switches have been brief and rapid, and in practice such operations will be complete before the operator has learned the line designation from the calling party. At this point, therefore, the operator depresses the 40 fifth or No. 4 office key 436 (see Fig. 4), the first or No. 0 thousands key 438, the fourth or No. 3 hundreds key 434, the sixth or No. 5 tens key 427, and the fifth or No. 4 units key 435. Before considering the 45 results of the depression of these keys, it will be observed that the cord finder sequence switch upon coming into its second position, closed and now maintains closed the sequence switch contacts 208, 209 and 50 210. The closure of the sequence switch contact 210 has established a circuit for the respective holding magnets 422 of the various sets of keys, such circuit being traced from battery through the holding 55 magnets 422 in parallel, conductor 244, sequence switch contact 210 to ground and back to battery. When, therefore, the keys above referred to were depressed, they were held in their depressed position by the various holding magnets 422 and will be maintained held in their depressed position until such time that they are no longer needed in connection with this particular call and may be used in connection with some other 60 65 call.

The depression of office key 436 has established a circuit from battery through conductor 502 (see Fig. 3), district register power magnet 503, conductor 507, back contact and armature 505 of the thousands 70 register stop relay 511, conductor 246, sequence switch contact 208, conductor 423, right contacts of the office key 436 to ground and back to battery. The closure of this circuit energizes the district register power 75 magnet 503 and the district register is started in motion. This motion of the district register will be continued until it reaches what may be called its fifth or No. 4 position, in which position the contact 80 device 509 thereon will be closed, as is indicated upon the drawings by the figure 4 adjacent thereto. At this time a circuit will be established from battery through the conductors 502 and 510, district register 85 stop relay 511, contact device 509, left contacts of the office key 436 to which said contact device is connected to ground and back to battery. The district register stop relay 511 will therefore be immediately energized, 90 attracting its armature and thereby opening the energizing circuit of the district register power magnet, causing the register to stop in its fifth or No. 4 position. The same movement of the armature 505 has closed 95 a circuit from battery through the sender sequence switch 336, sequence switch contact 306, conductor 512, front contact and armature 505 of the district register stop relay 511, conductor 246, sequence switch contact 100 208, conductor 423, right contacts of the depressed office key 436 to ground and back to battery. The closure of this circuit causes the sender sequence switch 336 to move out of its second position into its third 105 position, in which movement the energizing circuit just traced is open at the sequence switch contact 306. In the position to which the district register has been moved and has now stopped, but a single contact device 110 thereon other than the contact device 509 before referred to is closed, and this contact device is indicated at 617 (see Fig. 5).

The depression of the office key 436 has also caused the energization of the office register power magnet 504, such power magnet being connected by the armature 506 and its back contact of the office register stop relay 517 in parallel with the district register power magnet in the circuit heretofore 115 traced. The office register thereupon begins to move and continues its movement until the contact device 515 is closed in the fifth or No. 4 position of the office register, at 120 which time a circuit is closed for the office register stop relay 517 through the contact device 515 and the left contacts of the depressed office key. This causes the energization 125 of the office register stop relay, which thereupon attracts its armature 506, opening 130

the energizing circuit of the office register power magnet 504 and stopping the office register in its fifth or No. 4 position with the contact device 515 closed, as is indicated 5 on the drawings by the figure 4 adjacent thereto. The attraction of the armature 506 has also closed a circuit from battery through the cord finder sequence switch 222, sequence switch contact 212, sequence switch 10 contact 335, conductor 518, front contact and armature 506 of the office register stop relay 517, conductor 246, sequence switch contact 208, conductor 423, right contact of the depressed office key 436 to ground and 15 back to battery. The closure of this circuit causes the cord finder sequence switch to move from its fifth position into its sixth position, in which position the energizing circuit just traced is opened at the sequence 20 switch contact 212.

The office register in its fifth or No. 4 position has closed thereon in addition to the contact device 515 the contact devices 619, 620 and 618 as indicated on the drawings 25 for purposes to be hereinafter described.

As soon as in response to the depression of the office key the district and office registers have come into their set position and the sender sequence switch has moved into 30 its third position and the cord finder sequence switch into its sixth position, the district and office selection controlling operations will take place, and this is true whether the numerical keys, that is, the keys indicating 35 the designation of the desired line in the thousands, hundreds, tens and units banks of keys have been depressed or not. As a matter of fact, the district and office selection controlling operations take place 40 while the operator is depressing the numerical keys, indicating the designation of the desired line. Before considering therefore the effects of the depression of the numerical keys, there will be considered the operations 45 which are the result of the depression of the office key 436.

When the sender sequence switch 336 came into its third position, it closed at the sequence switch contact 309 what is known as 50 the fundamental circuit, or the selection controlling circuit, which circuit for district selection, which of course takes place first, may be traced as follows: from battery through the sequence switch contact 136, 55 district line relay 150, sequence switch contact 133, conductor 114, contact terminal 239 upon the cord finder, brush 234, conductor 114, sequence switch contact 309, stepping relay 701, conductor 113, back contact and 60 armature 721 of the cutoff relay 719, conductor 113, brush 233 upon the cord finder, contact terminal 238, conductor 113, sequence switch contact 106, to ground and 65 back to battery. This closure of the fundamental circuit has energized the district line

relay 150 (Fig. 1), and the stepping relay 701 (Fig. 5). The district line relay thereupon attracts its armature and closes a circuit for the district sequence switch from battery through such sequence switch, sequence switch contact 107, front contact and armature of the district line relay 150, back contact and armature 147 of the restoring relay 146 to ground and back to battery. The district sequence switch thereupon 70 moves into its third position, in which movement, however, it does not affect the fundamental circuit hereinbefore described, since the sequence switch contacts 106, 136 and 133 all remain closed in the third position 75 as well as in the second position. However, in the third position of the district sequence switch, the sequence switch contact 117 is closed and a circuit is thereupon established for the tripping spindle power magnet 68 80 from battery through such power magnet, sequence switch contact 117, front contact and armature of the district line relay 150, back contact and armature 147 of the restoring relay 146 to ground and back to 85 battery. The energization of the power magnet 68 causes the tripping spindle to begin to rotate. As has been hereinbefore described, the first movement of this tripping spindle closes the interrupter contacts 95 59 and 60, the contacts 59 remaining closed so long as the tripping spindle remains out of its normal position. It will be remembered, however, that the contacts 60 are opened each time the tripping spindle comes 100 into proper position to trip the succeeding latches associated with the brushes upon the selector switch carriage, the contacts 60, however, being closed each time the tripping spindle is passing from one such position to 105 the next.

The movement of the tripping spindle and the consequent closure of the interrupter contacts 60 has closed a shunt circuit to ground for the district line relay 150, maintaining such relay energized, but shunting and therefore deenergizing the stepping relay 701. Each time that the contacts 60 are opened, therefore, the stepping relay 701 will be energized and each time the contacts 110 60 are closed, stepping relay 701 will be deenergized, and this operation will continue 115 so long as the movement of the tripping spindle continues.

Let us turn now and see what results upon 120 the energization and deenergization of the stepping relay 701. When the fundamental circuit was first closed, the stepping relay 701 was energized coincident with the energization of the district line relay 150. The 125 armature 702 was therefore attracted and a circuit is closed from the battery 703 through the sequence switch contact 312, the first counting relay 711, back contact and armature 712 of the first counting relay 713, front 130

contact and armature 702 of the stepping relay 701 to ground and back to battery. The closure of this circuit causes the energization of the first counting relay 711 which closes at the front contact of its armature 714 a locking circuit for itself and prepares at the front contact of its armature 715 an energizing circuit for the first counting relay 713. When now, therefore, upon the first closure of the interrupter contacts 60 on the district selector, the stepping relay 701 was deenergized, its armature 702 in retracting opens the original energizing circuit of the first counting relay 711 without, however, deenergizing this relay since it has now locked up through its armature 714 and its front contact, and closes through its back contact a circuit for the first counting relay 713 from the battery 716 through the sequence switch contact 311, first counting relay 713, back contact and armature 715 of the second counting relay 711, front contact and armature 715 of the first counting relay 711, back contact and armature 702 of the stepping relay 701 to ground and back to battery. The energization of this first counting relay 713 closes for itself a locking circuit through its armature 717 and its front contact and prepares a circuit for the second counting relay 711 through its armature 712 and its front contact. It may also be observed that the original energizing circuit for the first counting relay 711 is now open at the back contact of the armature 712 of the first counting relay 713.

The subsequent energization of the stepping relay 701, due to the first opening of the interrupter contacts 60 as the movement 40 of the tripping spindle proceeds, causes a second energization of the stepping relay 701, which closes by its armature 702 and its front contact a circuit for the second counting relay 711, which circuit may be traced from the battery 703 through the sequence switch contact 312, second counting relay 711, back contact and armature 712 of the second counting relay 713, front contact and armature 712 of the first counting relay 713, front contact and armature 702 of the stepping relay 701 to ground and back to battery. The second counting relay 711 is thereupon energized, closing a locking circuit for itself similar to the one hereinbefore described in connection with the first counting relay 711, opening at the back contact of its armature 715 the original energizing circuit of the first counting relay 713 and preparing at the front contact of its armature 715 an energizing circuit for the second counting relay 713. Upon the subsequent deenergization of the stepping relay 701, the second counting relay 713 will be energized, closing a locking circuit for itself, opening the original energizing cir-

cuit for the second counting relay 711 and preparing an energizing circuit for the third counting relay 711 in a manner precisely analogous to the hereinbefore described operations of the first counting relay 713.

The successive counting relays 711 and 713 will continue to be energized and locked up in alternation by the alternate energization and deenergization of the stepping relay 701 in a manner which will be clearly understood from the just described operation of the first counting relays 711 and 713. This operation will continue until the counting relay 713 associated and connected to the closed contact 617 upon the district register is 75 reached. Immediately upon the energization of this counting relay 713, in this particular instance the fifth counting relay 713, a circuit will be established from battery through the cutoff relays 719, sequence switch contact 314, conductor 604, contact device 617 upon the district register, conductor 720, front contact and armature 717 of the last operated or fifth counting relay 713 to ground and back to battery. The closure of this circuit 80 causes the energization of the cutoff relay 719, which energization causes at the armature 721 the opening of the fundamental circuit hereinbefore described. It will be observed that this opening of the fundamental 95 circuit has taken place after five energizations and five deenergizations neither more nor less of the stepping relay 701, and that therefore at the time when this opening of the fundamental circuit takes place, the 100 tripping spindle is moving into its fifth position, that is to say, it is coming into position to trip the latch and thereby release the brushes adapted to coöperate with the individual row of sets of contact terminals upon 105 the district selector, which sets of contact terminals are connected to trunks leading to office switches apportioned to the fifth or No. 4 division of the system.

The energization of the cutoff relays 719 110 has by the attraction of their armature 722 closed a circuit through the sequence switch contact 310 for the sender sequence switch 336 and causes such sequence switch to move out of its third into its fifth position under 115 the influence of its special contact 301. In this movement of the sender sequence switch 336, the sequence switch contact 314 has been opened and the sequence switch contact 315 has been closed. Also the sequence 120 switch contact 308 has been closed, but the closure of this sequence switch contact is without effect in connection with the selection of the particular line assumed in this case and its utility will be hereinafter described. As the sender sequence switch was leaving its third position, it opened the sequence switch contacts 309, 310, 311 and 312, maintains these sequence switch contacts open in its fourth position, and has 130

closed them again in its fifth position. The opening of the sequence switch contacts 311 and 312 has released all of the locked up counting relays 711 and 713 by the opening 5 of the battery circuits thereto. The opening of the sequence switch contact 309 was for the purpose of maintaining the fundamental circuit open until such circuit was opened at the district sequence switch by 10 the opening of the sequence switch contacts 106, 136 and 138, the operation of which sequence switch contacts will now be described.

Upon the opening of the fundamental circuit by the attraction of the armature 721 of the cutoff relay 719, one of the ground connections completing the circuit of the district line relay 150 was opened. As soon 15 now, therefore, as the interrupter contacts 60 open, upon the tripping spindle coming into its fifth position, there will be no ground connection completing the circuit of the district line relay 150 and such relay will be deenergized. The effect of the de- 20 energization of this district line relay 150 is to close a circuit for the district sequence switch 101 through the sequence switch contact 138, back contact and armature of the district line relay 150, back contact and armature 25 147 of the restoring relay 146. The district sequence switch now moves into its fourth position. It will be observed that on coming into its fourth position, the district sequence switch has opened the fundamental circuit 113, 114 at the sequence switch contacts 106 and 133, and that furthermore this opening takes place before the fundamental circuit is again closed by the sender sequence switch contact 309. The closure of 30 the fundamental circuit by the closure of the sequence switch contacts 122 and 123 has not yet taken place, therefore, while the district sequence switch is in its fourth position, in which position the district selector is finding 35 an idle line in the selected bank, which operation in actual practice takes but a very short time, the fundamental circuit is maintained open and no change takes place in the sender or cord finder apparatus.

When the district sequence switch came 40 into its fourth position, it established for the selector power magnet 62 a circuit which may be traced from battery through the power magnet, back contact and armature of the test relay 152, sequence switch contact 45 121, sequence switch contact 118 to ground and back to battery. This causes the energization of the power magnet 62 and the brush carriage 22 will commence to move, first passing the brushes and latches by the tripping spindle and thereby causing the tripping of the selected (fifth) latch and the release of the fifth set of brushes and then trailing the released set of brushes 23, 24, 50 25 across the sets of contact terminals 27,

28, 29, of the bank with which they coöperate. In this latter movement, so long as the test brush 25 does not come in contact with the test terminal 29 of an idle line, sufficient potential will not be found to energize the test relay 151 and the brush carriage will continue its movement. As will hereinafter be pointed out, on all sets of terminals with which the selected brushes 23, 24, 25 come in contact, connected to a 75 trunk line which is already in use in connection with some other call, a shunt or low resistance path to ground will exist upon the test contact thereof. When, however, the selected brushes come in contact with the terminals of an idle trunk line, a circuit will be established from battery (see Fig. 7) through the office sequence switch contact 806, office restoring relay 823, the test conductor of the trunk line, test terminal 29, 80 test brush 25, sequence switch contact 120, closed as will be observed in the fourth position of the district sequence switch, right winding of the double wound test relay 151, and thence either through the spring 52, 90 arm 43 and plate 50 of the interrupter or through the test relay 152 and sequence switch contacts 116 and 118 to ground and back to battery. This circuit, since it carries full test potential, will energize the 95 double wound test relay 151, causing it to attract its armature and establish for itself a locking circuit through its left winding, which winding is of relatively low resistance and the circuit through this left winding of the double wound test relay will now 100 not only perform the function of maintaining this relay energized, but will establish immediately a low resistance path to ground from the test contact 29, making this test 105 contact of such electrical condition that it will test busy at all of the other district switches in which this trunk line appears.

The movement of the switch carriage 22, however, does not cease immediately upon 110 the selected brushes coming in contact with the terminals of an idle line, since the shunt to ground above referred to exists around the test relay 152, and this shunt will not be removed until the selected brushes are centered upon the terminals of the idle trunk line, at which time the interrupter arm 43 will no longer be in contact with the interrupter plate 50, and, the shunt being removed, the test relay 152 is immediately energized. As soon as the test relay 152 is energized, the circuit of the selector power magnet 62 is opened at the back contact of 115 its armature and an energizing circuit for the holding magnet 65 is immediately closed 120 at the front contact of such armature, which circuit may be traced from battery through the holding magnet 65, front contact and armature of the test relay 152, sequence switch contact 121, sequence switch contact 125 130

118 to ground and back to battery. It will therefore be apparent that as soon as the selected brushes are centered upon the terminals of the desired idle trunk line, the switch carriage 22 will be stopped with them in such position and held positively in such position by the holding magnet 65.

It should be particularly noted at this point that in the entire trunk hunting operation of the district selector the selected brushes 23, 24, which, until an idle line was found, have been making contact with the terminals 27, 28, connected to the talking strands of the various busy office trunks, have been entirely clear of any ground, battery or bridging connection and therefore no interference with such busy lines has taken place.

The energization of the test relay 152 as just described has also closed a circuit through the sequence switch contact 119 for the district sequence switch 101 in parallel with the holding magnet 65. The district sequence switch now moves out of its fourth position and into its sixth position under the influence of its special contact 102, opening the sequence switch contacts 118, 119, 120 and 121 and closing the sequence switch contacts 122 and 123 to extend the fundamental circuit over the selected trunk line to the office selector. As soon as this occurs, the fundamental circuit is again established, this time between the sender apparatus and the office selector, and may be traced as follows: from battery through the office line relay 821, office sequence switch contact 803, contact terminal 27 of the office trunk, contact brush 23 on the district selector, district sequence switch contact 123, conductor 114 to the stepping relay 701 and back by the conductor 113 through district sequence switch contact 122, brush 24 on the district selector, contact terminal 28, office sequence switch contact 805 to ground and back to battery. It will be recalled that while the district switch was selecting an idle trunk line and the district sequence switch was moving from its third to its sixth position, the sender sequence switch contact 809, which is included in the conductor 114 of the fundamental circuit, had been again closed by the sender sequence switch coming into its fifth position. Furthermore, that the counting relays had been released and the energizing circuit for the cut-off relays 719 had been opened both by the release of the locked up counting relays and by the opening of the sender sequence switch contact 314, so that the armature 721 is again retracted to close the break in the conductor 113 of the fundamental circuit. Therefore as soon as connection is made to the idle office trunk and the district sequence switch has reached its sixth position, the fundamental circuit will be again closed as traced, ener-

gizing the office line relay 821 and the stepping relay 701.

Before proceeding with the operations which result upon the energization of these two relays, it should be observed that the circuit heretofore traced through the office restoring relay 823 and the two district test relays 151, 152 has energized the office restoring relay 823 and caused it to attract its armatures 822 and 824, the armature 822 closing for the relay an energizing circuit independent of the sequence switch contact 806, as will be apparent from the drawings. It will be obvious also that this relay 823 will remain energized so long as the circuit through the district test relays and the test brush 25 upon the district selector is maintained, holding the armature 824 in its attracted position for purposes to be herein-after described. The energization of the stepping relay 701 by the closing of the fundamental circuit has energized and locked up the first counting relay 711 in a manner hereinbefore described and now well understood and the energization of the office line relay 821 has closed a circuit through its armature and front contact and the sequence switch contact 804 for the office sequence switch 801, driving such sequence switch from its first into its second position. The office sequence switch on coming into its second position establishes a circuit for the tripping spindle power magnet 68, through the sequence switch contact 807 and the front contact and armature of the office line relay 821. It furthermore closes the sequence switch contact 808, preparing the shunt circuit through the interrupter contact 60 similar to the shunt circuit hereinbefore described in connection with the similar contacts of the district selector. Due to the energization of the tripping spindle power magnet 68, the tripping spindle will commence to move, operating in its movement the interrupter contacts 60 and closing the interrupter contacts 59.

Upon each successive closure of the interrupter contacts 60, the stepping relay 701 will be deenergized to energize and lock up one of the counting relays 713 in the manner hereinbefore described and upon each successive opening of the interrupter contacts 60, the stepping relay 701 is again energized to energize and lock up an additional one of the counting relays 711. This intermittent energization and deenergization of the stepping relay 701 will continue until the counting relay 713 connected to and associated with the particular contact device now closed upon the office register is reached. In the case assumed this will be the fifth counting relay 713, the contact device on the office register which is now closed being the device 620. It will be observed that this fifth counting relay 713 will be energized upon

the fifth closure of the interrupter contacts 60 on the office selector, at which time the tripping spindle will be coming into its fifth position, that is, into position to trip the 5 fifth set of brushes on the office selector, which brushes are adapted to make contact with the terminals of trunk lines leading to the fifth or No. 4 office of the district heretofore selected. Upon the energization of 10 this fifth counting relay 713, a circuit will be established for the cut-off relays 719 through the sequence switch contact 315, conductor 605, contact device 620 upon the office register, conductor 720, and front contact 15 and armature 717 of the counting relay 713 to ground. The establishment of this circuit energizes the cut-off relays 719 which thereupon attract their armatures, opening the fundamental circuit of the back contact 20 of the armature 721 and closing an energizing circuit for the sender sequence switch 336 at the front contact of the armature 722. The sender sequence switch, due to the establishment of this latter circuit now moves 25 from its fifth into its sixth position, where it rests awaiting the registration of the designation of the desired line upon the numerical registers. It may be observed, however, that should this registration already 30 have been accomplished, the sender sequence switch 336 would continue into its seventh position through a circuit hereinafter to be traced and would rest in such position awaiting the reestablishment of the fundamental 35 circuit which will take place only when an idle trunk line has been selected and seized by the office selector. It will be furthermore observed that the movement of the sender sequence switch 336 out of its fifth position 40 has released all of the locked up counting relays and has opened the energizing circuit of the cut-off relays 719 at the sequence switch contact 315.

When the fundamental circuit was opened 45 by the cut-off relays 719 upon the fifth closure of the interrupter contacts 60 of the office selector, the original energizing circuit for the office line relay 821 was opened and this relay is now energized for a very 50 brief interval by the ground connection through the sequence switch contact 808 and interrupter contacts 60. As soon as the tripping spindle 40 comes fully into its fifth position, this ground connection will be opened 55 and the office line relay immediately de-energized, opening at the front contact of its armature the energizing circuit for the tripping spindle power magnet 68 and closing at the back contact of its armature a 60 circuit for the office sequence switch 801 through the sequence switch contact 809. As a result of this operation of the office line relay 821 therefore the tripping spindle comes to rest in its fifth position, that is, in 65 position to trip the fifth set of brushes upon

the selector, and the office sequence switch moves out of its second into its third position. This is the trunk hunting position of the office sequence switch, and in this position it will be observed that the fundamental circuit is no longer closed by the sequence switch contacts 803 and 805 and is not yet closed at the sequence switch contacts 815, 816. The sequence switch contacts 815, 816 however, being open in this 70 the trunk hunting position of the office selector apparatus no interference with busy lines will result from the contact with the terminals of busy trunk lines of the selected brushes 23, 24, precisely as was 75 the case during trunk hunting in the district selector. In this position, however, a circuit is closed for the selector power magnet 62 through the back contact and armature of the office test relay 831 and 80 the sequence switch contact 813. This energizes the power magnet and the brush carriage 22 begins to move in its first 85 movement passing the latches by the tripping spindle, so that the desired set of 90 brushes is released and then trailing such selected and released brushes over the sets of contacts connected with the trunk lines leading to the desired office. Precisely as in the district selector, so long as the test 95 brush 25 does not come in contact with a test terminal 29 on which is present a full testing potential, no result comes from such trailing contact and the brush carriage will 100 continue its rotation.

When, however, the test brush 25 comes in contact with the test terminal 29 upon which the full unshunted potential of the battery connected therewith exists, the double wound test relay 832 will be energized through a 105 circuit which may be traced as follows: from battery through the resistance 829, test contact terminal 29, test brush 25, sequence switch contact 812, right winding of the double wound test relay 832, and thence 110 either through spring 52, arm 43, plate 50 of the interrupter or through the test relay 831 and the sequence switch contact 811 and front contact and armature 824 of the office restoring relay 823 to ground and back to 115 battery. Upon the closure of this circuit with the full potential of the battery available for the test relay 832, this relay will be energized, attracting its armature and closing for itself a low resistance locking circuit 120 independent of the sequence switch contact 812 through its left low resistance winding. By the closure of this low resistance circuit to ground an immediate test condition is created on the test terminals of 125 the seized line, the potential of the test terminal 29 being so reduced that the corresponding test terminals associated with this trunk line at all of the other office selectors will test "busy" and interference therewith 130

while it is in use will be rendered impossible.

- For the operation of the office selector, as in that of the district selector, the switch carriage does not stop immediately when the 5 brushes come in contact with the contact terminals of an idle line and upon the establishment of the low resistance test circuit, the test relay 831 being shunted by the ground circuit through the interrupter plate 50. As soon, however, as the selector in its 10 movement centers the brushes squarely upon the terminals of the idle line, this ground connection through the plate 50 will be broken and the shunt having been removed 15 from around the test relay 831, this relay will be energized in series with the low resistance winding of the double wound test relay 832.
- Immediately upon the energization of the 20 test relay 831, the circuit for the power magnet 62 is opened and a circuit for the holding magnet 65 is closed through the front contact of its armature and the sequence switch contact 813. In this manner 25 the switch carriage is brought quickly and positively to rest with its brushes resting centrally upon the terminals of an idle trunk line leading to a group selector in the office in which the desired line terminates. The energization of the test relay 30 831 has also closed through its armature and front contact and the sequence switch contacts 813 and 814 a circuit for the office sequence switch 801, which drives such sequence switch out of its third position and it moves under the influence of its special contact 802 into its thirteenth position, in which it again comes to rest. In leaving 35 its third position, the office sequence switch opened the sequence switch contacts 812 and 814 and on coming into its fourth position it closed the sequence switch contacts 815 and 816, maintaining these latter contacts closed continuously to and including 40 its thirteenth position. Due to the closure of the sequence switch contacts 815 and 816, the fundamental circuit is prepared for re-establishment, this time extending from the 45 group switch shown on Fig. 8 to the sender apparatus as soon as the sender sequence switch comes into its seventh position, if it has not already done so.
- Due to the depression of the office key 50 alone, therefore, an idle interoffice trunk line leading to a group selector in the desired office has been selected. It will be furthermore observed that these operations have all taken place automatically without 55 any further or additional act on the part of the operator other than the mere depressing of the proper office key. The selected trunk line leading from the district selector to the office selector, which has been referred to as the office trunk, is a three wire

trunk circuit comprising the two "talking" strands, used also as a part of the fundamental circuit, and a third strand or "test" strand. The selected interoffice or group trunk on the other hand is a two wire trunk 70 comprising only the two talking strands, and from this point on all selection controlling operations, as well as restoration controlling operations, must take place over this two wire trunk. How these operations are performed and how this two wire trunk is kept clear at the time when it is necessary to use it for conversational purposes, will be hereinafter pointed out in detail.

Referring now again to the sender and 80 cord finder apparatus, it will be recalled that both the sender sequence switch and the cord finder sequence switch are now in their sixth positions and are awaiting the registration of the designation of the 85 desired line on the numerical registers. It will be observed, however, as has been hereinbefore referred to, that it is immaterial, so far as this registration is concerned, whether the sender sequence switch 836 is 90 in its sixth position or not, provided only that it had reached its third position, so that the energizing circuit for the cord finder sequence switch 222 is closed through the sequence switch contacts 335 and 212 95 upon the energization of the office register stop relay. This is necessary in order that the cord finder sequence switch may be driven into its sixth position, as has been hereinbefore described.

When the operator depresses the numerical keys indicating the numerical designation of the desired line, she closed, as soon as both the thousands digit key and the units digit key were depressed, a circuit which 105 may be traced as follows: from battery through conductor 502, through the power magnets 519, 525, 531 and 537 of the respective numerical registers and the back contacts and armatures 520, 526, 532 and 538 of the stop relays 545, 529, 535 and 541 of the respective numerical registers in parallel, conductor 247, cord finder sequence switch contact 209, conductor 429, right-hand contacts 430 of the depressed units key 110 435, conductor 431, right-hand contacts of the depressed thousands key 433 to ground and back to battery. The closure of this circuit causes the energization of the various power magnets of the respective numerical 115 registers and such numerical registers will begin to move to take up their set positions under the control of the closed contacts of their associated numerical keys. For example, the thousands register will move until its contact 522 is closed, which will be in the first or No. 0 position of the register. The hundreds register will move until it comes into the position in which its contact 528 will be closed, the fourth or No. 3 position. 120

125

130

The tens register will move until it comes into the position in which its contact 534 is closed, the sixth or No. 5 position. Finally the units register will move until it comes 5 into the position in which its contact device 540 is closed, which will be the fifth or No. 4 position of the register. It may be here observed that the order in which the registers arrive at their set position is of no moment whatever, the operation of the cord finder sequence switch 222, on which is effected the immediate results of the arrival of these registers in their set position, taking place in a definite order in response to 10 the operation of the respective stop relays 545, 529, 535 and 541, such operations being performed in a definite sequence regardless of the actual sequence of the operation of these relays in a manner which will be here- 15 after pointed out. It will also be observed that it is not necessary in some instances that one or more of the registers move at all. For example, if the hundreds register were already in its fourth or No. 3 position, the 20 register would remain in such position, the energizing circuit for its power magnet 525 being opened, immediately upon its establish- 25 ment, at the back contact of the armature 526 by the energization of the hun- 30 dreds register stop relay 529.

As the thousands register reaches the position in which its contact device 522 is closed, a circuit is established from battery through the conductor 502, thousands register stop 35 relay 545, contact device 522, the connected depressed thousands key 433 and the left contacts thereof to ground and back to battery. This energizes the thousands register stop relay 545 which attracts its armature 40 520, opening the circuit for the thousands register power magnet 519 and stopping the register in its first or No. 0 position. The attraction of the armature 520 has also closed a circuit for the cord finder sequence switch 45 222, which may be traced as follows: from battery through the cord finder sequence switch 222, sequence switch contact 213, conductor 524, front contact and armature 520 of the thousands register stop relay 545, con- 50 ductor 247, sequence switch contact 209, conductor 429, right contacts 420 of the depressed units key 435, conductor 481, right contacts of the depressed thousands key 433 to ground and back to battery. The closure 55 of this circuit causes the cord finder sequence switch 222 to move from its sixth into its seventh position.

When the hundreds register comes into its set position, its stop relay 529 will be 60 energized and its armature 526 attracted to establish a circuit for the cord finder sequence switch similar to the one just traced in connection with the thousands register. This circuit may be traced from battery 65 through the cord finder sequence switch 222,

sequence switch contact 214, conductor 530, front contact and armature 526 of the hundreds stop relay 529 to the conductor 247 and thence as in the circuit hereinbefore traced in connection with the thousands 70 register. If the hundreds register had reached its set position before the thousands register reached its set position, the circuit just traced for the hundreds register would not be established because the sequence 75 switch contact 214, which forms a part thereof, is not closed until the cord finder sequence switch reaches its seventh position, and, as has been before noted, this does not occur until the circuit through the armature 80 520 of the thousands register stop relay and the sequence switch contact 213 has been established.

Upon the closure, therefore, of the circuit through the armature 526 of the hundreds 85 register stop relay subsequent to the movement of the cord finder sequence switch into its seventh position, or if this circuit was already prepared by the attraction of the armature 526 before the cord finder sequence 90 switch reached its seventh position, as soon as the cord finder sequence switch reaches such position, this cord finder sequence switch will be again energized and move from its seventh into its eighth position, 95 where it will await the coming of the tens register into its set position and the consequent attraction of the armature 532 of the tens register stop relay. When the armature 532 of the tens register stop relay has 100 been attracted and the cord finder sequence switch has reached its eighth position regardless of which operation takes place first, the cord finder sequence switch will be moved by the closure of a circuit including 105 the conductor 536 and the sequence switch contact 215 from its eighth position into its ninth position, where again, if the armature 538 of the units stop relay has not already been attracted, it will await the attraction 110 of such armature. Therefore, again upon the attraction of the armature 538 of the units register stop relay 541 and the coming of the cord finder sequence switch 222 into its ninth position, regardless of which operation takes place first, the cord finder sequence switch energized by a circuit including 115 the conductor 542 and the sequence switch contact 216 moves out of its ninth position and under the influence of its special contact 201 moves continuously until it comes to rest in its fifteenth position.

Before considering the effects produced by the coming of the various numerical registers into their set position, it will be observed that the designation of the desired 125 line is now stored or registered upon these numerical registers and that so far as this particular call and the operation of the sender proper associated with the set of nu- 130

merical registers shown is concerned, the keys which have been up to this time used to control the registers are no longer necessary and may be used in connection with some 5 other call and in the control of another set of registers associated with a second sender apparatus. As soon as the cord finder sequence switch moved out of its ninth position, which it could only do when the complete 10 designation of the desired line was stored or registered upon the registers associated with this particular cord finder sequence switch, it opened the sequence switch contact 210, thereby deenergizing the holding magnets 422 and allowing the various depressed keys to assume their normal position in a manner usual and well understood and therefore not shown in detail. It may also be observed that the cord finder sequence 15 switch in leaving its ninth position opened the sequence switch contacts 208 and 209, thereby opening and maintaining open the circuits, the closure of which is necessary in order to energize the various register power 20 magnets 503, 504, 519, 525, 531 and 537. In this way all interference with the set 25 positions of the various registers is prevented during the use of this set of keys shown on Fig. 1 in connection with some other 30 call while controlling another set of registers associated with another sender apparatus. The multiple connections by which the keys are connected to the second sender and set of registers are shown at the lower portion 35 of Fig. 4.

The cord finder sequence switch on coming into its fourteenth position has closed the sequence switch contact 218, extending thereby and maintaining in its fifteenth position the original common energizing circuit comprising in part the conductor 111 from the various cord circuits of this operator's position to the second cord finder and sender apparatus typified by the cord finder sequence switch 272 upon the lower right-hand part of Fig. 2.

From an inspection of the drawings it will be noted that the arrangement of the sequence switch contacts 202 and 218 of the first cord finder sequence switch 222 associated with the first cord finder individual to this operator's position and the sequence switch contacts 275 and 224 of the second cord finder sequence switch 272 associated with the second cord finder individual to this operator's position is such that when both cord finders and their associated apparatus are idle, that is, having their sequence switches in their first or normal 50 positions, the circuit will extend through the sequence switch contact 275 and sequence switch contact 202 to the first cord finder sequence switch 222; that while the first cord finder sequence switch is in its positions 55 2 to 13 inclusive, that is, while the ap-

paratus associated with the first cord finder is using the various keys shown on Fig. 4 common to the two sets of apparatus, the circuit including in part the conductor 111 is entirely open, the sequence switch contacts 202 and 218 both being open. When, however, the first cord finder sequence switch reaches its fourteenth position, in which position the keys are no longer necessary for the proper establishment of the call in which the apparatus associated with this cord finder sequence switch is being used, the originating circuit is again closed and now extends to the second cord finder sequence switch 272 through the sequence switch contacts 275, 218 and 224.

If, at any time before the first cord finder sequence switch returns to its first or normal position, a second call should be originated at this operator's position, the second cord finder sequence switch 272 will move out of its normal position and the apparatus associated therewith not shown, but precisely similar to the cord finder apparatus, the sender apparatus and the register apparatus shown in detail associated with the first cord finder sequence switch, which duplicate apparatus is typified and indicated by the second cord finder sequence switch 272 and the multiple connections indicated upon the lower part of Fig. 4, will control the connection desired. In accomplishing this, the second cord finder sequence switch will move out of its first position, thereby opening entirely again the originating circuit by opening the sequence switch contacts 275 and 224. When in turn the second cord finder sequence switch reaches its fourteenth position, at which time the apparatus associated therewith is through with the keys shown on Fig. 4, the sequence switch contact 275 is again closed and the originating circuit is again extended and may be used in connection with the first cord finder sequence switch and its associated apparatus, provided this cord finder sequence switch 222 is again in its normal position, in which condition the sequence switch contact 202 will be closed.

In my invention, therefore, as embodied in the system shown, I provide a single set of keys controlling and operable in connection with two different sending or selection controlling devices arranged in such a manner that the operator is not interested in, and in fact does not know, which of the two sending or selection controlling devices will be used in any particular call, all that is necessary so far as she is concerned being that the depressed keys which she has used in connection with one call should be released before she begins to indicate on such keys the designation of a desired line in connection with a subsequent call. In this way it has been found that a single set of keys will accomplish all the controlling opera-

tions which it is possible for a single operator to initiate, all of the operations except the mere observance of the depressed or non-depressed position of the keys being automatic and independent of any mental or physical action on the part of the operator.

Taking up now the selection controlling operations which occur as a result of the numerical registers coming into their set position, it will first be recalled that the exchange in which the particular desired line terminates is an exchange of five hundred lines. One manner of arranging the five hundred lines of this exchange is to have their multiple terminals appear upon three different groups of final selectors, each of such selectors being designed to accommodate two hundred lines, that is to say, of the three groups of final selectors, two groups will each accommodate and carry the multiple terminals of two hundred lines of the exchange, and the third group of selectors will carry the multiple terminals of but a single hundred lines in the exchange. In such an arrangement I prefer that the first group of selectors should carry the terminals of the first two hundred lines of the exchange, that is, the 0 hundred lines and the 1 hundred lines, and that the terminals of these 200 lines shall be so arranged on each of the selectors of this group that the first ten sets of the first hundred, that is, Nos. 000 to 009, will be the first ten sets of contacts on the lowermost bank of contacts over which the lowest set of brushes upon the selector will pass in its movement and that the first ten sets of terminals of the second hundred, that is, Nos. 100 to 109, will be the second series of terminals on such lowermost bank of terminals, after they have passed over the terminals just before mentioned, that is, those of lines numbered 000 to 009. Correspondingly, on the second bank of the selectors of this same group, the brushes will first pass over the terminals of lines 010 to 019 and then over terminals 110 to 119. The other banks of terminals on these selectors will be arranged correspondingly; that is to say, brush selection in these final selectors will select the group of ten lines of the hundred in which the desired line appears, and having selected such group, the final or units selection will select, in a manner hereinafter to be described, the particular set of terminals individual to the desired line and select such set in the proper hundred, that is, in the first set of ten terminals in the selected bank, or in the second set of ten terminals in the selected bank according as the desired line is in the No. 0 or No. 1 hundred lines of the exchange.

Correspondingly the second set of final selectors carrying the No. 2 and No. 3 hundreds lines will have the first ten sets of ter-

minals of each hundred on the first bank, the second set of ten sets of terminals in each hundred on the second bank, and so on, these banks of terminals on each bank being arranged so that the brushes first pass over the ten sets of terminals of the No. 2 hundred and then pass over the ten sets of terminals of the No. 3 hundred. Since the exchange comprises only five hundred lines, the terminals of but a hundred lines, that is the No. 4 hundred lines will appear upon the third set of final selectors. These will be arranged ten sets on a bank and the brushes in their operative movement will begin to pass over these terminals as soon as the brush carriage starts to move in what may be referred to as its selective range, that is to say, in that part of its movement which takes place after the brushes have been tripped and at the time that the impulses are being sent back by the final selector over the fundamental circuit to the sender apparatus.

In an exchange comprising but five hundred lines, as in the one as med, what may be called thousands selection is unnecessary. Provision is therefore made for carrying the sender sequence switch through its seventh position when connection is being obtained to an exchange of this character. In order to accomplish this result, the contact 619 is provided on the office register, which contact will be closed whenever the office register is in position to control the selection of a trunk line leading to an exchange in which thousands selection is not necessary.

When now the cord finder sequence switch 222 moved out of its ninth position into its tenth position and then into its fifteenth position, it closed a circuit for the sender sequence switch 336 which may be traced from battery through the sender sequence switch 336, sequence switch contact 307, sequence switch contact 211, front contact and armature 288 of the test relay 229 to ground and back to battery. The sender sequence switch upon the establishment of this circuit moves from its sixth into its seventh position. The movement of the sender sequence switch into its seventh position, however, will not cause the closure of the fundamental circuit at the sequence switch contact 309 as might be expected for the reason that an energizing circuit has been established for the cut-off relays 719 in the sixth position of the sender sequence switch and is maintained in the seventh and eighth positions thereof. In these positions, therefore, the armature 721 is maintained attracted and keeps the fundamental circuit open until the sender sequence switch reaches its ninth position, to which position it will be driven by the closure of a circuit therefor through the sequence switch contact 310 and the armature 120

722 and its front contact consequent upon the maintained energization of the cut-off relays 719 by the circuit above referred to. This circuit referred to may be traced as follows: from battery through the cut-off relays 719, sequence switch contact 313, conductor 621, office register contact device 619, conductor 299, conductor 245, cord finder brush 232, contact terminal 237, conductor 115, sequence switch contact 110, back contact and armature 147 of the restoring relay 146 to ground and back to battery.

The sender sequence switch on leaving its eighth position, opens the sequence switch contact 313 and the cut-off relays will therefore be deenergized and allow their armatures to retract. Therefore, upon the sequence switch coming into its ninth position, the closure of the sequence switch contact 309 will reestablish the fundamental circuit provided the trunk line to the desired exchange has already been seized by the office selector, and if such trunk line has not been seized, the closure of the sequence switch contact 309 will prepare such circuit for closure when such line is seized. The fundamental circuit now established from the group selector may be traced as follows: from battery through the group line relay 871, sequence switch contact 853, contact terminal 27 upon the office selector, selected brush 23 on such selector, office sequence switch contact 815, contact terminal 27 upon the district selector, selected brush 23 on such selector, district sequence switch contact 123, conductor 114, through the sequence switch contact 309, the stepping relay 701 and the armature 721 of the cut-off relay 719, conductor 113, district sequence switch contact 122, selected brush 24 upon the district selector, contact terminal 28 upon such selector, office sequence switch contact 816, selected brush 24 upon the office selector, contact terminal 28 on such selector, group sequence switch contact 855 to ground and back to battery. The closure of this circuit energizes the stepping relay 701 and the group line relay 871. The energization of the stepping relay 701 causes the energization of the first counting relay 711 in a manner and with results hereinbefore fully described. The energization of the group line relay 871 establishes a circuit for the group sequence switch 851 through the armature and front contact of such relay and the sequence switch contact 854. The group sequence switch therefore moves out of its first and into its second position, in which position brush selection upon the group selector will take place.

A circuit is now established for the tripping spindle power magnet 68 which may be traced from battery through the power magnet, sequence switch contact 856, front contact and armature of the stepping relay 871

to ground and back to battery. The tripping spindle 40 will therefore commence to move, closing in a manner already described the contacts 59, 60. The intermittent closure of the contacts 60 during the movement 70 of the tripping spindle will shunt the stepping relay 701, the shunt connection being traced from the fundamental circuit through the office sequence switch contact 857 and the contact 60 to ground. For each position, therefore, that the tripping spindle of the group selector moves, the stepping relay 701 will be once energized and then deenergized. This intermittent energization of the stepping relay 701 will take place in the 80 instance assumed but twice before the cut-off relay 719 will be caused to be energized.

It will be recalled that the designation of the desired line is 354; therefore when the second counting relay 713 was energized, 85 the circuit was established for the cut-off relays 719, which may be traced from battery through such relays, the sequence switch contact 317, conductor 612, conductor 613, contact device 618 upon the office register, which it will be recalled is in its fifth or No. 4 position, contact device 622 upon the hundreds register, conductor 623, conductor 726, front contact and armature 717 of the second counting relay 713 to ground 90 and back to battery. The fundamental circuit will therefore be opened by the attraction of the armature 721 of the cut-off relays 719 and the tripping spindle of the group selector will come to rest in position to trip the second set of brushes upon such group selector, such set of brushes being adapted to hunt for and seize a trunk leading to an idle final selector in which the particular line desired terminates. It will also be observed that the energization of the cut-off relays 719 has again established a circuit through their armature 722 and the sequence switch contact 310 to move the sender sequence switch 336 from its ninth into its 100 eleventh position, in which movement the sequence switch by the opening of the sequence switch contacts 311 and 312 has released the locked up counting relays; it has also caused the momentary opening of the sequence switch contacts 309, 310 and has opened the sequence switch contact 317 and closed the sequence switch contact 318 for purposes now well understood.

Upon the opening of the fundamental circuit as the tripping spindle of the group selector is coming into position to trip the second set of brushes, the group line relay 871 will be dependent for its energization upon the ground connection through the interrupter contacts 60, and when such interrupter contacts open upon the spindle coming fully into its position for tripping the second set of brushes, the group line relay 871 will be deenergized, opening the circuit 110 125 130

heretofore traced for the tripping spindle power magnet 68 and thereby stopping the movement of the tripping spindle and establishing by such deenergization a circuit for the group sequence switch through the sequence switch contact 858. The group sequence switch 851 now moves from its second position and under the influence of its special contact 852 continues to move until coming to rest in its seventh position, which is the hunting position for the group selector. In this position of the sequence switch, therefore, a circuit is completed for the power magnet 62 of the group selector through the sequence switch contact 860 and the back contact and armature of the test relay 881, and the switch carriage 22 of the group selector begins to move, in the first movement thereof passing the brush latches past the tripping spindle in such a manner that the selected sets of brushes—in this case the second set—will be released, and then trailing these released brushes over the sets of terminals in the second bank of contacts, which terminals are connected to trunks leading to the group of final selectors in which the desired line appears. Here again as in the office and district selectors interference with busy trunk lines is prevented by maintaining the sequence switch contacts 866 and 867 open so that the released brushes 23 and 24 are clear.

As the released brushes now begin to pass over the various sets of terminals, the test brush 25 comes in contact with the test terminals 29 of the respective sets. So long as the test terminals 29 with which it comes in contact do not have thereon full battery potential, no operation will take place further than the continued movement of the brush carriage. As has been hereinbefore pointed out in connection with the district and office selectors, and as will be hereinafter apparent in the case of the group selector itself, the test terminal 29 of a trunk that is idle will have thereon the full potential of the battery connected hereto through the final sequence switch contact 937 and the resistance 957. If, however, any shunt to ground exists on this test conductor on a multiple terminal thereof in any of the group switches upon which the trunk line with which it is associated appears, insufficient potential will exist thereon to operate the double wound office test relay 882. If, on the other hand, full unshunted battery potential appears upon this test conductor, a circuit will be established from battery through the resistance 957, final sequence switch contact 937, test terminal 29 upon the group selector, test brush 25 of the selected set of brushes on such selector, office sequence switch contact 862, right winding of the double wound test relay 882 and thence either through the

spring 52, arm 43 and plate 50 of the interrupter, or through the test relay 881 and the sequence switch contact 861 to ground and back to battery. This circuit will cause the energization of the double wound test relay 882 which, by the attraction of its armature, closes for itself a low resistance locking circuit through its left winding, thereby maintaining itself energized and establishing immediately a test condition upon the test terminal of the selected trunk in all of the group selectors in which it appears. As has been before noted in connection with the district and office switches, the movement of the switch carriage does not cease immediately upon the selected brushes thereof coming in contact with the line which is seized, the movement of the switch carriage ceasing only when the ground connection through the interrupter plate is opened as the selected brushes are centered squarely upon the terminals of the seized line. Upon the opening of this ground connection, the shunt is removed from around the test relay 881 and this relay is energized and attracts its armature, opening the circuit of the power magnet and closing the circuit of the holding magnet 65 through the front contact of its armature and the sequence switch contact 863, thereby bringing the brush carriage to a stop and holding it with the selected brushes in proper contact with the terminals of the seized trunk line.

The energization of the test relay 881 has also closed through the front contact of its armature a circuit for the group sequence switch 851 which now moves out of its seventh position and comes to rest in its fourteenth position, the circuit for the test relay 881 being maintained in its eighth position and controlled between its eighth and fourteenth position by the special sequence switch contact 852. It will be observed that the group sequence switch moves idly from its ninth to its fourteenth position, that is to say, while certain sequence switch changes take place during this period, no operation takes place in the group selector or its associated apparatus after the closure of the fundamental circuit through to the final trunk and its connected final selector apparatus by the closure of the sequence switch contacts 866 and 867 as the group switch comes into its ninth position. This idle movement of the group sequence switch is for the purpose of permitting the energization of the final line relay 941, see Fig. 9, and the consequent movement of the final sequence switch 901 from its first to its second position in a manner to be hereinafter described, so that the final sequence switch contact 937 will be opened before the group sequence switch comes into its fourteenth position. Therefore, when the group se-

quence switch does come into its fourteenth position, the test relay 881 will be no longer energized owing to the removal of the battery connection therefrom by the 5 opening of the sequence switch contact 937 and the group sequence switch will come to rest. At this time and hereafter until the final selector has been restored to normal, a test condition is maintained upon the seized 10 trunk line leading to the final selector by reason of the fact that as soon as the final sequence switch contact 937 is opened, which occurs immediately upon the seizure of the final selector by the group selector, the normal 15 battery connection to the test conductor of the trunk line is opened and no potential whatever exists upon such conductor. The marginal test relay 882 of any other group selector attempting to seize this trunk line cannot 20 therefore be energized over this test conductor, and as a result no seizure of this trunk line while it is in use can take place. It may at this point be observed that by 25 means of the sequence switch contacts 853, 855 and 859 the fundamental circuit has been kept closed, energizing the stepping relay 701 when the sender sequence switch reaches its eleventh position, and will be maintained closed through such sequence 30 switch contacts until it is closed through to the final selector apparatus in the ninth position of the group sequence switch, and upon the movement of such sequence switch out of its ninth position, the sequence switch contacts 35 853 and 859 are opened so that the fundamental circuit depends for its integrity entirely upon the apparatus of the final switch at the final selector. In connection with the group selector it may be noted that 40 as the group sequence switch 851 comes into its eighth position, the sequence switch contact 865 is closed, establishing the restoring circuit for the tripping spindle power magnet which will be maintained through the 45 interrupter contacts 59 until such tripping spindle is again in its normal position. This restoration of the tripping spindle may take place at this time without any detrimental effect upon the associated apparatus for the 50 reason that the tripping spindle having performed its function of releasing the selected set of brushes upon the selector will not be used again for any purpose whatever during this particular connection. It may also be 55 observed that a similar operation takes place in connection with the office selector when the office sequence switch comes into its fifth position and in the district selector when the district sequence switch comes into its seventh position, which position, however, it 60 has not yet reached.

The fundamental circuit is now closed through to the final selector apparatus in the manner above described and may be 65 traced as follows: from battery through the back contact and armature 942 of the battery control relay 943 through the final line relay 941, sequence switch contact 903, contact terminal 27 upon the group selector, selected brush 23 upon such selector, office 70 sequence switch contact 866, contact terminal 27 upon the office selector, selected brush 23 upon such selector, office sequence switch contact 815, contact terminal 27 upon the district selector, selected brush 23 upon such selector, district sequence switch contact 123, conductor 114, and thence through the sender sequence switch contact 309, the stepping relay 701, back contact and armature 721 of the cut-off relay 719 and back 75 by way of conductor 113, district sequence switch contact 122, selected brush 24 upon the district selector contact terminal 28 upon such selector, office sequence switch contact 816, selected brush 24 upon the office selector, contact terminal 28 on such selector, group sequence switch contact 867, selected brush 24 on the group selector, contact terminal 28 on such selector, final sequence switch contact 904, armature 944 and its back contact 80 of the battery control relay 943 to ground and back to battery.

The closure of this fundamental circuit as just traced maintains the stepping relay 701 energized (it will be remembered that this relay was energized by the closure of the group sequence switch contact 859) and energizes the final line relay 941, which attracts its armature and closes a circuit for the final sequence switch 901, which may 95 be traced as follows: from battery through such sequence switch, sequence switch contact 905, conductor 961, front contact and armature of the final line relay 941 to ground and back to battery. The final sequence switch thereupon moves into its second position, opening the sequence switch contact 937 for purposes hereinbefore described and also opening the sequence switch contact 905 in its original energizing circuit. 100 On coming into its second position, the final sequence switch closes the sequence switch contacts 906 and 907 and brush selection by means of the movement of the tripping spindle now takes place in a manner precisely 105 similar to that which has already been described in connection with the district, office and group selectors. The circuit for the tripping spindle power magnet includes, as will be readily observed from the drawings, 110 the sequence switch contact 906, the conductor 961 and the front contact and armature of the line relay 941. The ground connection for shunting the stepping relay 701 including the interrupter contacts 60 in this 115 case includes the sequence switch contact 907 and is connected to the fundamental circuit in such a manner that when the interrupter contacts 60 are closed, the final line relay 941 will be maintained energized, but the 120 125 130

stepping relay 701 will be shunted and therefore deenergized. As the tripping spindle moves, therefore, the stepping relay 701 will be intermittently energized and deenergized, locking up the various counting relays in a manner hereinbefore fully described. This operation will continue until the counting relay associated with and connected to the particular contact device is reached which is closed upon the register now operatively associated with the counting relays by the sequence switch contacts shown at the lower left-hand corner of Fig. 2. At this particular time it will be observed that it is the tens register which is associated with the counting relays, the sequence switch contact 318 being the one closed. The last counting relay, therefore, that will operate during brush selection on the final selector in the case assumed will be the sixth counting relay 713, the particular contact device on the tens register which is closed at this time being the contact device 608 closed in the sixth or No. 5 position of the register. It may be observed at this time that there are no additional contact devices upon the tens register other than the ten shown on Fig. 5, that is to say, that no translation takes place in connection with the tens register such as does take place in connection with the hundreds and units registers under the control of the contacts thereon and contacts in the office register. When this particular counting relay 713 has been operated, the cutoff relays 719 will be energized in a manner hereinbefore described, their energizing circuit passing this time, however, through the sequence switch contact 318, the conductor 614 and the tens register contact device 608. The energization of the cutoff relays, as before, opens the fundamental circuit and drives the sender sequence switch out of its present position into its next stopping position which, in this case, will be the thirteenth position thereof. This movement of the sender sequence switch has, as has been before described, again released the locked up counting relays and for a brief period opened the sequence switch contacts 309 and 310 for purposes hereinbefore described. It has also opened the sequence switch contact 318 and closed sequence switch contact 319.

The opening of the fundamental circuit just described which took place upon the energization of the sixth counting relay 713, occurred as the tripping spindle 40 of the final selector was coming into its sixth position, that is to say, into the position in which it would select the set of brushes adapted to coöperate with the sixth bank of contact terminals upon this switch, which bank of terminals contains the terminals of lines numbered 250 259 and 350 to 359, as has been hereinbefore described. When the

latch selecting spindle now comes fully into its sixth position, that is, the position just referred to, the interrupter contacts 60 will be again opened, and since both the ground connection through the interrupter contacts 70 and the fundamental circuit are open at this time, the final line relay 941 will be deenergized, opening the power circuit for the tripping spindle power magnet and bringing the tripping spindle to a stop 75 in the position to trip the desired set of selector brushes. The deenergization of the final line relay 941 has also established a circuit for the final sequence switch 901, which may be traced through the sequence 80 switch contact 909, the armature 960 and its back contact of the battery control relay 943, and the back contact and armature of the final line relay 941. The final sequence switch 901 therefore leaves its second position 85 and under the influence of its special contact 902 moves into its fifth position.

When the sender sequence switch 336 comes into its thirteenth position and closes the sequence switch contact 309, the fundamental circuit is again established precisely as just previously traced, energizing the stepping relay 701 and the final line relay 941. When the final sequence switch reaches its fifth position, a circuit is closed through 90 the sequence switch contact 910, the conductor 961 and the front contact and armature of the final line relay 941 for the brush carriage power magnet 62 and the brush carriage will now begin to rotate. In the 100 first portion of this movement the tripping spindle will release the selected set of brushes 23, 24, 25 and in the continued movement of the brush carriage it will trail these released brushes over the sets of contact terminals in the bank of terminals with which they coöperate. In the movement, however, of the final brush carriage as it trails these terminals over the various sets of contact terminals, the interrupter at the 105 top of the final selector will close a circuit to ground from the fundamental circuit through the sequence switch contact 908, the interrupter springs 48, 49 and the sequence switch contact 907 as the brushes 110 approach each set of contact terminals. When, however, the selected brushes rest upon each succeeding set of contact terminals, this ground connection will be broken to the interrupter. It will, therefore, be 120 apparent that the movement of the brush carriage over the final selector, passing the selected brushes over the various sets of contact terminals, will produce the intermittent energization and deenergization of 125 the stepping relay 701 precisely as the movement of the latch tripping spindle has done in the selections hereinbefore described, one energization and deenergization of the stepping relay taking place before the brushes 130

rest upon each succeeding set of contact terminals. Interference with busy lines is here prevented during this movement by maintaining the sequence switch contacts 926, 927, 930 and 931 open in the various selecting and testing positions of the final sequence switch.

- It will be recalled that the units register is in its fifth or No. 4 position and that therefore the contact devices 626 and 627 thereon are closed. It will be furthermore recalled that the sender sequence switch contact 319 is now closed so that it is the units register which is now particularly associated with the counting relays. When the fifth counting relay 713 becomes energized as a result of the continued movement of the final selector brush carriage, no circuit will be established for the cutoff relay 719 as might be expected, since the circuit through the contact device 626 upon the units register is open at the contact device 628 upon the hundreds register. (It may be here observed that this circuit is also open at the contact device 602 upon the office register). That is to say, since the desired line is in the fourth or No. 3 hundred lines of the exchange, the contact device 625 upon the hundreds register is closed and the contact device 628 upon such register is open, so that the final selector will select in the second set of ten terminals upon the selected bank rather than in the first set of ten terminals upon such bank.
- The brush carriage of the final selector will therefore continue to move and it will be only upon the fifteenth energization and deenergization of the stepping relay 701 that the circuit for the cutoff relays 719 will be established through the sequence switch contact 319, conductor 615, contact device 625 upon the hundreds register, conductor 629, contact device 627 upon the units register, and front contact and armature 717 of the fifteenth counting relay 713. Upon the energization of the cutoff relays 719, due to the establishment of this circuit, the fundamental circuit is permanently open so far as this particular connection is concerned, first by the attraction of the armature 721 and then by the opening of the sequence switch contact 309 upon the movement of the sender sequence switch 336 out of its thirteenth position due to the attraction of the armature 722. Before considering the operations of the final selector apparatus due to this opening of the fundamental circuit, it will be observed that the sender sequence switch on leaving its thirteenth position, moves continuously under the control of its special contact 301 until it reaches its eighteenth position. As the sender sequence switch 336 comes into its fourteenth position, it establishes a circuit through the sequence switch

contact 305, which may be traced as follows: from battery through the district sequence switch 101, sequence switch contact 107, conductor 248, contact terminal 236 upon the cord finder, brush 231, conductor 337, sender sequence switch contact 305, conductor 245, cord finder brush 232, contact terminal 237 upon the cord finder, conductor 115, district sequence switch contact 110, back contact and armature 147 of the restoring relay 146 to ground and back to battery. The closure of this circuit causes the district sequence switch to move from its sixth into its seventh position, opening the circuit just traced at the district sequence switch contact 107 and also opening at contact 110 the energizing circuit of the reset relay 332 and the cord finder test relay 229. Upon the deenergization of these two relays both the cord finder sequence switch and the sender sequence switch will be restored to normal position and the entire sender apparatus will be ready for use in controlling some other connection.

The deenergization of the test relay 229 established at the back contact of its armature 228 a circuit for the cord finder sequence switch 222, which thereupon moved and under the control of its special contact continued to move until it came into its first or normal position, in which only its contact 202 is closed. The deenergization of the reset relay 332 established a circuit for the sender sequence switch 336 through the sequence switch contact 303 and the back contact and armature 334 of the reset relay 332. The sender sequence switch, therefore, on coming into its eighteenth position will continue to move due to the establishment of this circuit until it comes into its first or normal position, in which position only its contacts 302 and 304 are closed. The entire sender apparatus and the cord finder apparatus with which it is associated have now returned to their normal position, and provided the second sender apparatus is not now utilizing the keys shown in Fig. 4, such sender apparatus and cord finder may be used in connection with such keys to control the establishment of another connection.

Returning now to the description of the operation of the final selector, it will be recalled that the selected and released brushes 23, 24, 25 are just coming in contact with the terminals of the desired line. When these brushes rest squarely upon these terminals, the ground connection through the interrupter springs 48, 49 will be opened and the fundamental circuit being already opened, the final line relay will be without current and will therefore retract its armature. The circuit for the power magnet 62 will therefore be opened and a circuit for the holding magnet 65 will be closed through the sequence switch contact 911,

the armature 960 and its back contact of the battery control relay 948 and the back contact and armature of the final line relay 941. In this manner the final selector switch is brought positively to a stop with the released brushes thereof in proper contact with the terminals of the desired line. It will be observed, however, that the brushes 23, 24, which are in contact with the talking terminals of the desired line are entirely clear of any bridge, battery or ground connections and will remain clear until after the desired line has been tested and found idle, none of the sequence switch contacts 926, 927, 930 and 931 being closed until after the test has taken place. In this manner no interference will result with lines already busy due to the passage of the selected brushes over the terminals of such lines and their intermittent contact therewith.

The deenergization of the final line relay 941 at the end of units selection has closed a circuit for the final sequence switch 901 exactly as it did before in the second position of this sequence switch. The sequence switch, therefore, moves out of its fifth position and continues to move under the influence of its special contact 902. In this movement of the sequence switch a double test will be made of the test terminal 29 of the desired line.

Assuming first that the desired line is an ordinary subscriber's line as shown at 971, 972 (Fig. 10) and is idle. When the final sequence switch 901 reaches its sixth position a circuit will be established from the middle or neutral point of the battery 99 through the right winding of the double wound test relay 945, sequence switch contact 912, polarized test relay 946, test brush 25 of the selected set of brushes, test terminal 29 of the selected line, test wire of the selected line, through the cutoff relay 997 of such line to the positive or grounded pole of the battery 99. Assuming, as before noted, that the line selected is idle and that therefore no other final selector brushes and no cord circuit is connected to the terminals of such line, the full potential of the positive portion of the battery 99 will pass through the polarized test relay 946 and the right winding of the double wound marginal test relay 945, causing the relay 945 to attract its armature and causing the polarized test relay to move its armature in a clockwise direction. The attraction of the armature of the relay 945, due to its energization as just described, closes a circuit for the test relay 949, such circuit passing through the sequence switch contact 914. The test relay 949 thereupon energizes and attracts its armatures 950, 951, 952, closing a locking circuit for itself through the sequence switch contact 915 and its armature

951. It also establishes a circuit from the middle or neutral point of the battery through the armature 950 and its front contact, left winding of the marginal test relay 945 to the test brush 25 of the selected set of brushes. This circuit provides a substitute path from the test terminal of the selected line in place of the path heretofore described through the polarized test relay 946 and the right winding of the marginal test relay 945. This substitute path is of somewhat lower resistance and as such creates a test condition upon the test terminal of the selected line at all of the final selectors in which such line appears, this test condition being produced by the substantial lowering of the potential of such test terminals by this low resistance path from the test terminal with which the test brush 25 is now connected.

Under the assumption, therefore, that the selected line is idle and is an ordinary subscriber's line, it having been tested and found idle in the sixth position of the sequence switch, no further test is necessary, and when the sequence switch arrives in its eighth position it will find a circuit already established through the sequence switch contact 922 and the front contact and armature 952 of the test relay 949 and it will continue in its movement. Before the final sequence switch, however, reaches its ninth position, it will be found by referring back to the district selector apparatus, Fig. 1, that the trunk line, which has heretofore been considered only as a part of the fundamental circuit, but which now forms the talking and controlling circuit, has been closed, independent of any ground or battery connection through a bridge including the two portions of the right winding of the induction coil 154, the sequence switch contacts 125 and 126 and the district line relay 150 and the condenser 153 in parallel. It will be recalled that the last described operation of the district selector apparatus was the movement of the district sequence switch 101 from its sixth into its seventh position. This sequence switch, however, will not stop in the seventh position in the ordinary operation of the system, but will pass on to its eighth position due to the establishment by the closure of the sequence switch contacts 119 and 121 in the seventh position of an energizing circuit therefor through the front contact and armature of the test relay 152 and to ground either through the back contact and armature 147 of the restoring relay 146, or the sequence switch contact 118. The district sequence switch, therefore, comes into its eighth position. The district line relay 150 being now included in the trunk circuit, it and the final line relay 941 are both energized in series over a circuit from

battery through the armature 942 and its back contact of the battery control relay 943, final line relay 941, sequence switch contact 916 which is closed in the sixth position of the final sequence switch, tip conductor of the trunk circuit through the group, office and district selectors, one portion of the right-hand winding of the repeating coil 154, sequence switch contact 126, sequence switch contact 125, district line relay 150, the other portion of the right-hand winding of the repeating coil 154, ring conductor of the trunk circuit through the district, office and group selectors, armature 944 and back contact thereof of the battery control relay 943 to ground and back to battery. This circuit just traced also it will be observed includes the left-hand winding of the repeating coil 962. The closure of this circuit energizes the district line relay 150 and a circuit is established for the district sequence switch 101 through the sequence switch contact 107, the front contact and armature of such relay and the sequence switch contact 118. This causes the district sequence switch to move into its ninth position.

When the final sequence switch reaches its eighth position, it finds as above described a circuit established for itself that causes it to continue its movement until it comes into its eleventh position. As the final sequence switch left its ninth position, the sequence switch contact 915 was opened, but a locking circuit for the test relay 949 was maintained through the sequence switch contact 923 and the front contact and armature of the final line relay 941, which is now energized in series with the district line relay 150 in the circuit heretofore traced. Consequently upon coming into its eleventh position, the final sequence switch will find the same energizing circuit prepared for itself that it found in its eighth position, and it will continue its movement and come to rest in the twelfth position, which is the ringing position of the final selector apparatus. In the twelfth position of the final sequence switch, the sequence switch contact 924 is closed and the polarity test relay 946 is again included in a test circuit to the test terminal of the selected line in order to test the polarity of the potential existing thereon. This test relay will receive sufficient potential given the positive part of the battery 99, in spite of the parallel circuit through the left winding of the marginal test relay 945, to cause it to move its armatures as before in a clockwise direction. At the same time the sequence switch contacts 926 and 927 will be closed and a circuit will therefore be established from the positive source of ringing current indicated to the right of the polarity test relay 946, through the armature 947 of this relay, through the ringing control relay 953, sequence switch contact 927, brush 24 of the

selected set of brushes, terminal 28 of the selected line out over such line and through the ringer thereof at the substation indicated at 972, back over the other side of the line through the terminal 27 upon the final selector, brush 23 of the selected set of brushes, sequence switch contact 926 to ground and back to the current source. The ringing current through this circuit will be sufficient to signal the called subscriber, but it will be insufficient, so long as the switch hook at his substation is depressed, to energize the ringing control relay 953. When, however, the called subscriber, in response to the operation of his ringer, removes the receiver from its switch hook, a path of low resistance is closed through the transmitter and switch hook at his substation and sufficient of the positive ringing current will now pass through the circuit just previously traced to energize the ringing control relay 953. This relay thereupon immediately attracts its armature and closes a circuit for the final sequence switch 901, which includes the sequence switch contacts 928 and 908 and the front contact and armature of such relay 953. The final sequence switch thereupon moves into its thirteenth position, which is the talking position of the final selector apparatus.

As soon as the final sequence switch comes into its thirteenth position, the sequence switch contacts 930 and 931 are closed, which complete the talking and battery supply circuit of the called subscriber, such circuit including between the two portions of the right winding of the repeating coil 962 the supervisory relay 954 and the battery 958, which battery supplies the called subscriber with talking current. Immediately upon the establishment of this talking and battery supply circuit, the supervisory relay 954 is energized and thereupon attracts its armature, closing an energizing circuit for the battery control relay 943 through the sequence switch contact 929. The battery control relay is therefore energized and attracts its armatures. The first result of the attraction of the armatures of the relay 943 is the deenergization of the district line relay 150 and the final line relay 941. The district line relay 150 in retracting its armatures establishes an energizing circuit through the back contact thereof and the sequence switch 138 for the district sequence switch 101, which thereupon moves into its tenth position, which is the talking position for the district selector apparatus. The attraction of the armatures 942 and 944 of the battery control relay 943 has, however, not only caused the deenergization of the final line relay 941, but has bridged such relay directly across the two sides of the trunk circuit in parallel with the condenser 955 and the

trunk circuit is now complete at both ends thereof with no battery contained therein. This is the talking condition of the trunk circuit, the respective ends thereof being inductively connected with the calling and called subscribers' battery supply and talking circuits by the repeating coil 154 on the one hand, and the repeating coil 962 on the other hand.

10 It will be observed that substantially simultaneous with the attraction of the armature 960 of the battery control relay 943, the armature of the final line relay 941 was retracted and no circuit therefore was established for the final restoring relay 956 through the armatures of such battery control and line relays. It may be observed, however, that at this time the control of the apparatus now rests with this relay 956, which relay in turn is controlled by the position of the armature 960 of the battery control relay 943 and the armature of the final line relay 941. So long as these armatures are not both in attracted position or both in retracted position at the same time, this second supervisory relay 956 will not be energized. It may be observed that this relay is made slow-acting, as is indicated upon the drawings, so that the movement of the armatures need not be absolutely simultaneous.

15 20 25 30

Restoration.—Conversation having finished, the subscribers replace their receivers upon the respective switch hooks. The effect of this act by the calling subscriber is to light the lamp 156 by a circuit including the back contact and armature of the supervisory relay 145 and ground through the sequence switch contact 137 or front contact and armature 148 of the cord relay 142. The lighting of this lamp indicates to the operator that the calling subscriber has replaced his receiver upon the hook. From the called end the replacement by the called subscriber of his receiver upon the hook, opens the energizing circuit of the supervisory relay 954, which, by the retraction of its armature, opens the circuit of the battery control relay 943. This relay thereupon allows its armatures to retract, again including battery in the circuit of the district line relay 150 and the final line relay 941, so that these relays immediately attract their armatures. Again it will be observed that the retraction of the armature 960 of the battery control relay 943 was substantially simultaneous with the attraction of the armature of the final line relay 941, so that the slow-acting restoring relay 956 will not be operated at this time. The energization of the district line relay, however, has by the attraction of its armature closed a circuit for the lamp 157, which circuit may be traced through the sequence switch contact 130, front contact and arm-

ture of the district line relay 150 and the sequence switch contact 118. The lighting of this lamp 157 indicates to the operator that the called subscriber has replaced his receiver upon its switch hook. The restoration of the entire apparatus now awaits the withdrawal by the operator of the plug 141 from the jack 61 of the calling subscriber. Upon the withdrawal of the plug, the consequent deenergization of the cord relay 142 establishes a circuit for the listening sequence switch 176, which is at this time in what is known as its off-listening position, that is, the eighth position thereof. The listening sequence switch will thereupon move into its first or normal position, in which position, by the closure of the sequence switch contact 179, a circuit is established for the district sequence switch 101, which may be traced as follows: from battery through such sequence switch 101, sequence switch contact 135, listening sequence switch contact 179, back contact and armature 144 of the supervisory relay 142 to ground and back to battery. The district sequence switch now moves from its tenth into its fourteenth position. On leaving the tenth position, the district sequence switch opened the energizing circuit of the district line relay 150 and the final line relay 941 at the sequence switch contacts 125 and 126.

The deenergization of the final line relay 941 causes a circuit to be established through the back contact of its armature and the back contact of the armature 960 of the battery control relay 943 for the final restoring relay 956 including the sequence switch contact 932. The final restoring relay by the attraction of its armature closes an energizing circuit for the final sequence switch 901, which circuit will be maintained until the deenergization of the final restoring relay 956 by the opening of the sequence switch contact 932 as the final sequence switch leaves its fourteenth position. The final sequence switch therefore will continue to move until it reaches its sixteenth position. On coming into its fifteenth position, the final sequence switch closed the sequence switch contact 936 and maintains such contact closed until it leaves its eighteenth position, for purposes which will hereinafter appear. On leaving its thirteenth position, the final sequence switch has opened the sequence switch contacts 930 and 931, rendering the brushes 23 and 24 clear, so that in restoration they will cause no interference with busy lines while passing over the terminals thereof.

In the thirteenth position of the sequence switch while conversation was going on, the tripping spindle was restored to its normal position by the circuit through its power magnet, the sequence switch contact 983 and

the interrupter contacts 59. As the sequence switch left its thirteenth position, the locking circuit for the test relay 949 was opened at the sequence switch contact 915 and the armatures 950, 951, 952 were consequently retracted. By the retraction of the armature 950, the energizing circuit through the left winding of the double wound marginal relay 945 is opened, allowing such relay to 5 retract its armature and removing the test condition from the test terminal of the line with which connection has just been made. When now the sequence switch reaches its 10 sixteenth position, a circuit is established for the switch carriage power magnet through the sequence switch contact 917, back contact and armature of the test relay 945 and sequence switch contact 914. Due to the energization of the power magnet, the 15 brush carriage will again begin to rotate and will continue in this movement until a full rotation is completed and the carriage comes again into its normal position. As the switch carriage comes into its normal position, however, the arm 43 of the interrupter at the top of the carriage comes into contact with the plate 46 thereof. A 20 circuit is now established from the middle or neutral point of the battery 99 through the right winding of the test relay 945, sequence 25 switch contact 913, plate 46, arm 43 and to ground through the frame of the selector carriage, causing the energization of the test relay 945 which, by attracting its armature, 30 opens the circuit of the power magnet, closes the circuit of the holding magnet and thereby brings the selector to rest in its normal position. The attraction of the armature of the test relay 945 has also closed a circuit 35 for the test relay 949 through the sequence switch contact 914; the test relay 949 thereupon attracts its armatures and closes at the front contact of its armature 952 a circuit for the final sequence switch 901 40 through the sequence switch contact 922. The final sequence switch now moves from its sixteenth position into its first or normal position, restoring in such movement all of the final apparatus which is not already in 45 normal condition to normal. It may be here observed that in the movement of the switch carriage to its normal position, the brushes were moved past the restoring roller and the selected brushes were restored to their 50 normal or latched position.

As a final sequence switch came into its 55 sixteenth position, it closed the sequence switch contact 937, which reestablished an energizing circuit for the test relays 881 and 882 of the group selector, the sequence switch of which it will be recalled is now in its fourteenth position. The energization 60 of the relay 881 has closed a circuit through its armature and front contact for 65 the group selector sequence switch 851,

which now moves into its sixteenth position; this is the restoring position for the group selector.

The group sequence switch immediately upon coming into its fifteenth position, 70 which it will do before the final sequence switch leaves its eighteenth position, closes the sequence switch contact 868 which places a bridge across the trunk line leading to the district selector, thereby maintaining the 75 district line relay energized. During the restoration of the final selector, this district line relay was kept energized by the closure of the final sequence switch contact 936. Just before the final sequence switch returns 80 to normal position, the group sequence switch is operated to close the sequence switch contact 868, as hereinbefore noted. This sequence switch contact will be maintained closed until the restoration of the 85 group selector is complete. The purpose of this bridge is to prevent the removal of the test condition on the interoffice or two wire trunk line by the initiation of restoration of the office selector until the group selector 90 is fully in its normal position. As will be hereinafter pointed out, the restoration of the office selector is now under the control of the district line relay.

It may be found advisable in some installations to omit the sequence switch contact 868 in order to hasten the completion of restoration of the various selectors and upon the coming of the final sequence switch into its normal position the restoration of 100 the district selector and then the office selector will begin. Under these circumstances, however, the interoffice trunk will be left unguarded for a very brief interval which may be measured from the time the 105 office selector begins to restore until the time when the group selector reaches its normal position. This period, however, will be very brief at its longest, since in reality during the operating interval while the district line 110 relay is retracting, the district sequence switch is moving out of its fifteenth position, and the office restoring relay is retracting, the group selector will be in a fair way toward reaching its normal position.

In the sixteenth position of the group sequence switch, a circuit is established for the brush carriage power magnet 62 through the sequence switch contact 860 and the back contact and armature of the test relay 881, 120 the energizing circuit of which was opened as the group sequence switch left its fourteenth position by the opening of the sequence switch contacts 861 and 862. This energizing circuit for the power magnet 62 125 will be maintained and the switch carriage will continue to move until, upon coming into its normal position, a circuit is completed from battery through the sequence switch contact 864, resistance 880, plate 46, 130

5 arm 43 and spring 52, all of the interrupter at the top of the switch carriage, test relay 881, sequence switch contact 861, to ground and back to battery. This energizes the test relay 881 which, by the attraction of its armature, opens the circuit for the power magnet 62 and closes the circuit for the holding magnet 65 through the sequence switch contact 863. The brush carriage is 10 in this manner brought positively to rest in its normal position, the brushes having been restored to their latched condition in passing by the restoring roller during the restoring movement of the switch carriage. The attraction of the armature test relay 881 has also closed a circuit for the group sequence switch 851, which now moves out of its sixteenth position and comes to rest in its first or normal position, all of the group 15 selector apparatus now again being in its normal condition.

It will be recalled that the last described operation of the district selector apparatus was the movement of the district sequence switch 101 out of its tenth position, which movement will continue until it reaches its fourteenth position. Subsequent to this, it was described how the trunk circuit was bridged at the final selector apparatus by the closure of the final sequence switch contact 936, and later by the closure of the group sequence switch contact 868. In this, the fourteenth position, the district line relay will be energized over a circuit including the sequence switch contacts 136 and 131 and the trunk circuit.

Upon the opening of the group sequence switch contact 868, or in case this sequence switch contact is omitted upon the opening of the final sequence switch contact 936, the district line relay 150 will be deenergized and close a circuit through the back contact of its armature and the sequence switch contacts 138, 118 for the sequence switch 101. This circuit, which will be also maintained in the fifteenth position of the sequence switch, will drive the sequence switch out of its fourteenth through its fifteenth and into its seventeenth or normal restoring position under the control of its special contact 102. On leaving its fifteenth position, the district sequence switch, by opening the sequence switch contact 116, has opened the circuit of the test relays 151 and 152 and the office restoring relay 823. The office restoring relay 823, by the retraction of its armature 824, closes a circuit for the office sequence switch 801, which will thereupon move out of its thirteenth and into its sixteenth or restoring position. Restoration, therefore, of the office and district selector switches and their associated apparatus now takes place simultaneously, a test condition being constantly maintained on the test terminal of the trunk line leading to this particular

20 office selector due to the fact that until the office selector apparatus has come fully into its normal position, no potential whatever will be present upon any of the test terminals of this trunk line in any of the district 70 selectors in which it appears. This results from the fact that the sequence switch contact 806 is not closed until the apparatus is in its normal condition, the deenergization of the office restoring relay 823 having, by 75 the retraction of its armature, removed the battery connection, which has up to this time been present upon the test terminals since the first energization of this relay 823 in the first position of the office sequence switch, 80 as has been heretofore described. The restoration of this office selector is accomplished by the establishment in the sixteenth position of the office sequence switch of a circuit for the power magnet 62 through the 85 back contact and armature of the test relay 881 and the sequence switch contact 813. Due to the energization of the power magnet by the closure of this circuit, the office selector brush carriage begins to move, continuing its rotation from the point at which it had stopped upon seizing the group or interoffice trunk, and will continue to move until it reaches again its normal position, 90 in which movement the released brushes by 95 coming in contact with the restoring roller will be restored to their normal or latched position.

As the switch carriage comes into normal position, the interrupter arm 43 comes in 100 contact with the interrupter plate 46 and a circuit is established from the battery through the armature 822 and its back contact of the office restoring relay 823, resistance 830, plate 46, arm 43, and spring 52, 105 all of the interrupter at the top of the brush carriage, test relay 881, sequence switch contact 811 to ground and back to battery. Immediately upon the closure of this circuit, the test relay 881 is energized and attracts 110 its armature, opening at the back contact thereof the circuit of the power magnet 62, closing at the front contact thereof and through the sequence switch contact 813 a circuit for the holding magnet 65. In this 115 way the office selector switch is brought positively to rest in its normal position. The same movement of the armature of the test relay 881 has also closed a circuit 120 through its front contact and sequence switch contacts 813 and 814 for the office sequence switch 801, which now moves from its sixteenth position and comes to rest in its normal position, and all of the apparatus forming a part of the office selector apparatus 125 is again in its normal condition, the sequence switch 806 being again closed and thereby placing the full idle battery potential upon the various test terminals of the trunk line associated with this office selector. 130

- It will be recalled that the last described operation of the district selector apparatus was the movement of the district sequence switch into its seventeenth position. In this 5 position of the district sequence switch, a circuit was established for the power magnet 62 of the district selector through the back contact and armature of the test relay 152, sequence switch contacts 121 and 118. 10 The district selector brush carriage will now move, continuing its rotation from the contacts of the seized line until it reaches its normal position, when a circuit will be established from battery through the armature 149 and its front contact of the restoring relay 146, resistance 155, plate 46, arm 43, spring 52, all of the interrupter at the top of the selector switch carriage, test relay 152, sequence switch contacts 116 and 118 to 15 ground and back to battery, it being observed that the restoring relay 146 is energized and maintained energized in the sixteenth, seventeenth and eighteenth positions of the district sequence switch by the closure 20 of the sequence switch contact 132. Upon the closure of this circuit through the test relay 152, it attracts its armature and opens at the back contact thereof the circuit of the power magnet 62, closing at the same time a circuit for the holding magnet 65 through the sequence switch contacts 121 and 118, thereby bringing the district selector switch carriage positively to rest in its normal position. The same movement of 25 the armature of the test relay 152 has closed a circuit through the sequence switch contacts 119, 121 and 118 for the district sequence switch 101 which now moves out of its seventeenth position and comes to rest in its first or normal position. All of the 30 district selector apparatus is now again in its normal condition, the tripping spindle having been returned to its normal position by the closure of the sequence switch contact 124 when the district sequence switch 35 reached its seventh position in a manner hereinbefore described.

The entire apparatus which has been used in the establishment of the desired connection assumed and in conversation thereover has now been returned to normal and this is indicated to the operator by the extinguishment of the lamp 156, which has been maintained lighted ever since the replacement 40 of the calling subscriber's receiver to its switch hook 52 by a circuit through the back contact and armature of the supervisory relay 145 and the sequence switch contact 137. It is by the opening of this sequence switch contact that as the district sequence switch leaves its eighteenth position just before coming into its normal position, this lamp is extinguished.

Attention will be here called to the fact 45 that in the restoration of each of the vari-

ous selector switches as just described, as well as in the various other restorations to be hereinafter described, all of the selected and released brushes 23 and 24 are dead, that is to say, without ground, battery or 70 bridging connection during the restoring movement of the brush carriage, and therefore any interference with busy lines, with the talking terminals of which they may come in contact, is positively prevented. 75

Test of busy line.—If, when the final selector came into contact with the terminals of the desired line, such line was already busy, either because connection has been made therewith by some other final selector, 80 or because such line as a calling line had a plug similar to the plug 141, Fig. 1, inserted in its answering jack, the normal battery potential which, when the line is idle, exists upon its test terminal, would have been reduced by the connection to ground through the test brush and test relay 945 in a manner hereinbefore described, or through the cord relay 142. Therefore when the final sequence switch was passing through its 85 sixth position and the circuit was established, hereinbefore traced, through the right winding of the double wound marginal test relay 945 and the polarity test relay 946 to the test brush 25, insufficient potential would be found upon the test terminal 29 to energize the marginal test relay 945. During the continued movement, therefore, of the final sequence switch 901, the test relay 949 will not be energized. It 90 will be observed, however, that although the marginal test relay 945 has not been energized, the polarized test relay has received sufficient current from the positive portion of the battery 99 to cause it to move its 95 armatures in a clockwise direction, and therefore when the final sequence switch 901 reaches its eighth position, a circuit will be closed through the sequence switch contact 922 and the armature 948 of the polarized test relay 946 to move it out of its 100 eighth position. Upon coming into its eleventh position in which position the circuit of the polarized test relay 946 is open and its armatures have returned to their 105 normal position, the final sequence switch will come to rest, since no circuit is provided therefor through the armature 952. Furthermore, since the marginal test relay 945 remains unenergized, a circuit is established 110 in the eleventh position of the final sequence switch through the sequence switch contact 917, the back contact and armature of the marginal test relay 945 and the sequence switch contact 914 for the brush carriage 115 power magnet of the final selector, and due to the closure of this circuit and the consequent energization of this power magnet, the final selector brush carriage will again begin to rotate and will continue this rota- 120

tion until it reaches its normal position in which rotation, as has been hereinbefore pointed out, the brushes 23 and 24 are dead and cause no interference with busy lines with which they may make passing connection. Upon arrival of the brush carriage in its normal position, a circuit is established from the middle or neutral point of the battery 99 through the right winding of the marginal test relay 945, sequence switch contact 913, plate 46 and arm 43 of the interrupter at the top of the brush carriage and through the frame of such brush carriage to ground. Full potential of the positive portion of the battery will now pass through the marginal test relay 945 and it will be energized, opening at the back contact of its armature the circuit of the power magnet 62 and closing at the front contact of its armature a circuit for the holding magnet 65 through the sequence switch contact 921. The selector switch carriage is thus brought positively to rest in its normal position. The movement of the armature of the relay 945 has also closed a circuit through its front contact and the sequence switch contact 914 for the test relay 949, which now pulls up and by the attraction of its armature 951 closes for itself a locking circuit through the sequence switch contact 915. The energization of the test relay 949 has also closed a circuit through its armature 952 and the front contact thereof and the sequence switch contact 922 for the district sequence switch, and such sequence switch now moves out of its eleventh position. On coming into its twelfth position, the sequence switch finds prepared for itself a circuit through the sequence switch contact 925, the plate 46 and arm 43, both of the interrupter on the brush carriage and to ground through the frame of such brush carriage. This circuit, which is maintained also in the thirteenth position of the final sequence switch, drives the sequence switch through its twelfth and thirteenth positions and the sequence switch comes to rest in its fourteenth position.

It may be here observed that in passing through the twelfth position, which is the ringing position of the final sequence switch, nothing occurred under the circumstances assumed for the reason that none of the brushes upon the switch carriage were in contact with any line terminals, the switch carriage being in its normal position and the brushes having been returned to their latched position in passing by the restoring roller during the restoring movement of the brush carriage.

Furthermore it will be observed that since there was no circuit closed through the brushes 23, 24, the supervisory relay 954 was not energized in the thirteenth position of the sequence switch and consequently the

battery control relay 943 was not energized in such position of the sequence switch. When, however, the sequence switch reached its fourteenth position, a circuit was intermittently closed for the battery control relay 943 through the sequence switch contact 934 and the interrupter 963. The first time that this circuit is closed upon the consequent energization of the battery control relay 943 the battery connection from the trunk circuit at the back contacts of the armatures 942 and 944 is removed and the district line relay 150 deenergizes and closes a circuit for the district sequence switch 101 through the back contact of its armature and the sequence switch contacts 138 and 118 driving the sequence switch out of its ninth position, in which it will be recalled it now is, into its tenth position. Upon the deenergization of the battery control relay 943, when the interrupter opens the intermittent circuit just previously traced, battery is again supplied over the trunk circuit and the district line relay 150 will be again energized, closing a circuit at the front contact of its armature, through the sequence switch contacts 130 and 118 for the supervisory lamp 157. The continued intermittent energization and deenergization of the battery control relay 943 will now result in an intermittent lighting of the supervisory lamp 157 through the intermittent energization and deenergization of the district line relay 150. It will be observed that during this intermittent energization and deenergization of the battery control relay 943, the restoring relay 956 will not be operated, since the energization of the battery control relay 943 accomplishes practically simultaneously the deenergization of the final line relay 941, and vice versa, so that at no time are the armature 960 of the battery control relay 943 and the armature of the final line relay 941 both either in retracted or attracted position at the same time during this operation.

The intermittent lighting of the supervisory lamp 157 indicates to the operator that the desired line is busy and she informs the calling subscriber of this fact. To accomplish this, she depresses her individual listening-in key 197, which drives the listening sequence switch 176 out of its eighth position and such sequence switch continues to move through its first position on account of the existence of the circuit hereinbefore described through the sequence switch contact 178, the listening sequence switch coming to rest in its fifth position, in which position it will be recalled the operator is in conversational connection with both ends of the trunk circuit and consequently through the plug 141 with the calling subscriber. In this movement of the listening sequence switch to its fifth position the closure of the

sequence switch contact 182 has driven any other listening sequence switch of this operator's position which happened to be in its fifth or listening-in position into its eighth 5 or off-listening position.

- The operator now completes her duties with regard to this unsuccessful call by removing the plug 141 from the jack of the calling subscriber. This act initiates the 10 restoration of the entire apparatus which has been used in connection with the call precisely as hereinbefore set forth, with the exception that the final selector switch is already restored to its normal position. 15 Therefore, when the district sequence switch reaches its fourteenth position, it establishes an energizing circuit for the final line relay 941 independent of the battery control relay 943 and therefore, upon the next subsequent 20 energization of the battery control relay 943 both the battery control relay 943 and the final line relay 941 will be energized. This will cause the energization of the restoring relay 956 by a circuit which has been previously traced and the final sequence switch 25 will be driven out of its fourteenth position. It may be here observed that the test relay 949 was energized by a circuit through the front contact and armature of the marginal 30 test relay 945 (energized by a circuit through the sequence switch contact 913) and sequence switch contact 914 when the sequence switch came into its fourteenth position, and therefore that no energizing circuit for such 35 sequence switch existed in the fourteenth position thereof through the sequence switch contact 935.

- When the final sequence switch reaches its sixteenth position, it finds prepared for 40 itself a circuit through the sequence switch contact 922 and the front contact and armature 45 952, the marginal test relay 945 being maintained energized in this position by the circuit through the sequence switch contact 913, since the brush carriage is in its normal 50 position and therefore the test relay 949 is also maintained energized as has been described. In all other particulars restoration after an unsuccessful call will take place precisely as was described after the conclusion of a successful call.

Private branch trunk line selection.—Let it be now assumed that the terminals selected, in the manner hereinbefore described 55 in detail, were a set of terminals connected to one of a plurality of trunk lines leading, for example, to a private branch exchange. Such being the case, it is necessary that means be provided whereby if such trunk 60 line is busy and there are other trunk lines leading to the same private branch exchange, any one of which would equally well serve the purpose of the calling subscriber, for moving the selector brushes on

65 to the terminals of such trunk lines suc-

cessively until an idle such trunk line has been found, or failing to find an idle line, all of the trunk lines being busy, the selector brush carriage should be again brought to its normal position and a busy 70 signal sent back over the trunk circuit to the operator and the calling subscriber. In order to accomplish these results, the terminals of all of the trunk lines leading to the private branch exchange are usually 75 placed adjacent to each other upon a single bank of such sets of terminals on the group of final selectors in which they appear. The numerical designation of the first of these trunk lines, that is, the one with which the 80 brushes of the final selector in their movement would first make contact, is the only number for this private branch exchange which is listed in the directory. All calls, therefore, for this private branch exchange 85 would first select in the final selector the set of terminals designated by the number listed. If the trunk line connected with this set of terminals is idle at this time, connection will be made therewith, as in the 90 case of an ordinary subscriber's line, with the single difference that the armatures of the polarity test relay 946 being unmoved in the twelfth position of the sequence switch, negative ringing current rather than 95 positive will be sent out over the seized line to operate the signaling device associated therewith. If, on the other hand, this first trunk line is busy at that time, the brushes of the final selector will move into contact 10 with the next succeeding set of terminals connected to another trunk line leading to the private branch exchange desired, and if such line is idle, it will be seized and connection be completed therewith without 1 connection either the operator or the calling subscriber being aware that the line seized is not the line indicated by the particular numerical designation. Should the second trunk line be busy, the brushes of the final selector will 1 continue in their movement until an idle line is found, or if all the trunks to this particular private branch exchange are at that time busy, until it has tested all of them when the busy signal will be sent back 1 to the calling operator.

The apparatus and connections associated with the various private branch exchange trunk lines of a group differ in no way from those of the ordinary subscribers' lines, except that the cut-off relays of such lines, three of which are shown, for example, as 979, 980 and 981 on Fig. 10, are connected to the negative or free pole of the battery 99 rather than to the positive or grounded pole thereof. It is necessary in addition, however, that immediately succeeding the set of terminals connected to the last of a group of private branch exchange trunk lines upon a final selector, there must be 1

connected an ordinary subscriber's line in which the test terminal is connected through its cut-off relay 997 to the positive or grounded pole of the battery 99, or, failing such ordinary subscriber's line, the group of trunk lines must be succeeded by a dead set of terminals, the test terminal of which is connected to ground through an ordinary resistance, as is plainly shown on Fig. 10.

Assuming now, therefore, that the selected set of terminals, the description of the selection of which has been hereinbefore set forth in detail, was the set of terminals on the final selector switch connected to the trunk line 979 (see Fig. 10). If this trunk line was at that time idle, the circuit established in the sixth position of the final sequence switch could be traced from the middle or neutral point of the battery 99 through the right winding of the marginal test relay 945, sequence switch contact 912, polarity test relay 946, test brush 25, test terminal 29 of the selected line shown as 979, test conductor of such line and cut-off relay associated with such line to the negative or free pole of the battery 99.

The full potential of the negative portion of the battery 99 would, therefore, pass through the cut-off relay of the line, the polarity test relay 946 and the marginal test relay 945 energizing such relays. The energization of the polarity test relay 946 is without effect at this time, but the energization of the marginal test relay 945 closes, by the attraction of its armature, the circuit for the test relay 949 which, by attracting its armature, locks itself up and also closes the low resistance energizing circuit through the left winding of the marginal test relay 945, maintaining such relay energized and creating the test condition upon the test terminals of the selected line. The test relays 945 and 949 having been energized in this manner will be maintained energized in the eighth position of the district sequence switch and therefore the failure of the polarity test relay 946 to be energized in the eighth position of the final sequence switch will be without effect, connection will be completed, the signaling device associated with the trunk line operated, conversation established and restoration accomplished precisely as has been fully described with relation to a connection with an ordinary subscriber's line. Assuming, however, that the first of these private branch exchange trunk lines indicated as 979 is busy when the selector brushes come in contact therewith and test it for its busy or idle condition. In this case as the final sequence switch passes through its sixth and seventh positions, insufficient battery potential will be found upon the test terminal 29 of the desired line to energize the marginal test relay 945 over the circuit traced. Its armature,

therefore, will remain retracted and the test relay 949 will remain unenergized. Furthermore the armatures of the polarity test relay 946 will remain in their normal position. When now the final sequence switch reaches its eighth position, it will stop in such position since the two circuits therefor, one through the armature 952 and its front contact of the test relay 949, and the other through the armature 948 and its alternate contact of the polarity test relay 946 are both open. A circuit, however, is established for the power magnet 62 of the selector brush carriage, which may be traced from battery through such power magnet, sequence switch contact 917, back contact and armature of the marginal test relay 945, sequence switch contact 918, normal contact and armature 948 of the polarity test relay 946 to ground and back to battery. The selector brush carriage will thereupon advance the selected brushes 23, 24, 25 to the next set of terminals upon the coöperating bank where a new test will take place, the circuit for which may be traced as before from the middle or neutral point of the battery 99, through the right winding of the marginal test relay 945, sequence switch contact 912, polarity test relay 946, test brush 25, but this time through the test terminal and test conductor of the trunk line 980, and thence through the cut-off relay of such line to the negative or free pole of the battery 99. If this line is idle at this time, the full electrical potential of the negative portion of the battery will pass through this circuit and the marginal test relay 945 will be energized. This will cause the attraction of the armature of this relay, opening the circuit of the power magnet 62 of the brush carriage at its back contact and closing the circuit of the holding magnet 65 through the sequence switch contact 921 at its front contact, thereby stopping the brush carriage and bringing the selected brushes positively to rest in contact with the terminals of the line indicated as 980. The same movement of the armature of the marginal test relay 945 closes a circuit for the test relay 949 from battery through such relay, front contact and armature of the marginal test relay 945, sequence switch contact 918, normal contact and armature 948 of the polarity test relay 946 to ground and back to battery. The closure of this circuit causes the immediate energization of the test relay 949, which attracts its armature, closes a locking circuit for itself as hereinbefore described through its armature 951, closes the substitute energizing circuit for the test relay 945 through its low resistance left winding, thereby placing a test guard upon the terminals of the seized line through its armature 950 and providing an energizing circuit for the final sequence switch 901 by 130

way of the sequence switch contact 922 through its armature 952. The operation of the final selector apparatus will now take place from this point on through ringing, 5 conversation and restoration precisely as has been hereinbefore described with relation to the connection established with an ordinary subscriber's line.

Assuming, however, that the second trunk 10 line indicated as 980 upon the drawings was also busy. Again insufficient current would pass through the marginal test relay 945 to energize such relay, and the circuit for the power magnet 62 being maintained, the 15 brushes will continue in their movement until they come upon the terminals of the third trunk line, indicated as 981, where again the test will be made for the busy or idle connection of this trunk line, and if 20 such line is idle it will be seized, whereas on the other hand, if such line is busy, the selector brushes will still continue in motion. When the brushes of the final selector have thus tested the terminal of 25 each of the trunk lines of a group, whether such group comprise two trunk lines or an entire bank of trunk lines, and has found all such trunk lines busy, they will continue in motion until they 30 come in contact with the next succeeding set of terminals beyond such group. As soon as contact is made with this set of terminals, the motion of the selector switch carriage and the selected brushes thereon 35 will cease, whether, in the case this set of terminals is connected to an ordinary subscriber's line, such line is busy or idle, and this is accomplished in the following manner: As soon as the test brush 25 comes in 40 contact with the test terminal 29 of such set of terminals, the circuit through the polarity test relay 946 and the right winding of the marginal test relay 945 hereinbefore traced, will be supplied by the positive portion 45 of the battery 99 and the polarity test relay 946 will move its armatures in a clockwise direction, thereby opening the circuit of the brush carriage power magnet 62 at the normal contact of the armature 948 and thereby stopping the movement 50 of the switch carriage. The same movement of the armatures of the polarity test relay 946 closed a circuit through the alternate contact of the armature 948 and 55 the sequence switch contact 922 to drive the final sequence switch 901 out of its eighth into its eleventh position, where it will stop and restoration will begin as has been hereinbefore described in connection with the 60 attempted seizure with a busy ordinary subscriber's line. As before noted, this will take place whether the terminals with which the brushes finally come in contact were those of either a busy or an idle line, 65 and this is for the following reason: Ob-

viously, if the line were a busy line, the marginal test relay 945 would not be energized and restoration would then take place precisely as in connection with an attempted seizure of a busy ordinary subscriber's 70 line. If, on the other hand, the terminals with which the brushes finally came in contact were those of an idle line, sufficient current would pass through the marginal test relay 945 to energize it. However, it 75 will be observed that in this position no circuit would be established for the test relay 949, since simultaneous with the energization of the marginal test relay 945, the polarity test relay 946 would be energized, 80 and since the final sequence switch is now in its eighth position, no current would be supplied through the armature of the marginal test relay 945 for the test relay 949.

The test relay 949 not having been energized in the eighth position of the final sequence switch, due to the opening at this time of both the sequence switch contact 914 and the normal contact of the armature 948 of the polarity test relay 946, 90 this test relay 949 will remain unenergized in the eleventh position of the sequence switch, since although the sequence switch contact 914 is closed at this time the energizing circuit through the right winding of the marginal test relay 945 has been opened at the sequence switch contact 912 and its armature now being retracted, no circuit is established for the test relay 949. The final sequence switch having come to 95 rest in its eleventh position, the restoration of the selector will now take place precisely as was the case after the attempted seizure of a busy ordinary subscriber's line and the busy signal will be returned to the operator in the fourteenth position of the final sequence switch as was described in that case. From that point on further restoration will take place as described.

When the selected brushes came in contact 11 with the set of terminals of the desired line, as has been described, in accordance with the numerical designation of such line indicated upon the depressed operator's keys, these selected brushes were centered upon the 11 terminals of such line in a manner which has been heretofore described, such centering being under the control of the shunt circuit established through the sequence switch contact 907, the interrupter springs 48 and 49 1 and the sequence switch contact 908. Such line having been, for example, a private branch exchange trunk line and busy, when the brush carriage moved the selected brushes into contact with a set of terminals 1 connected to another private branch exchange trunk line of the same group, which we will assume was idle, the selected brushes will be centered upon the terminals of this trunk line by a circuit including the sequence 1

switch contact 919. This circuit, which may be traced from the middle point of the battery 99 through the sequence switch contact 919, interrupter contacts 49, 48, sequence switch contact 920 to the sequence switch contact 912, will maintain a shunt around the right winding of the marginal test relay 945 until, when the brushes are centered upon the terminals of the line, this shunt is removed by the opening of the interrupter contacts 48, 49 and the marginal test relay will be energized. It will be observed, however, that this shunt around the right winding of the marginal test relay 945 in no way affects the circuit through the polarity test relay 946, so that the only effect which this shunt has is to prevent the opening of the circuit to the switch carriage power magnet 62 by the energization of the marginal test relay 945 until the selected brushes 23, 24, 25 are properly centered upon the terminals of the line which is seized.

Party line selection.—If the substation with which connection is desired is one of those connected upon a party line, it will be necessary that when the final selector has brought its brushes into contact with the terminals of such line that it determine and properly connect with the terminals of such line the particular character of ringing current necessary to signal the particular substation desired. In connection with the showing of the party line 973, (see Fig. 10) it will be observed that such party line has connected thereto four substations 974, 975, 976 and 977, and that such party line appears upon the final selectors at four different points as indicated by the four sets of connections, the talking conductors of which are in multiple, shown extending to the left upon Fig. 10 of the drawing. These four sets of connections associated with the party line represent each, individually, one of the substations upon such line as will be herein-after pointed out. It may be here observed that the terminals individual to the various substations of this party line need not appear one after another upon the final selectors, nor is it necessary even that they all appear upon the same group of selectors, but they may be so arranged and distributed as may be best adapted for the traffic conditions of the exchange. It will be noted from the drawings that the party line has associated with it, in addition to the two talking conductors forming a part thereof, two test conductors, one of such test conductors appearing at two of the sets of terminals individual to two of the substations, and the other of such conductors appearing at the other two sets of terminals. Also associated with this party line is the usual answering jack 998, the sleeve of which is connected to one of the test conductors before mentioned, and there is shown at the lower left-hand

corner of Fig. 10 the relay apparatus by which the busy or idle condition of the party line is determined and the signaling apparatus individual to the line is controlled.

The various signaling devices located at the substations of the party line are shown as biased ringers connected two each to the respective sides *a* and *b* of the line. It will be observed, therefore, that to ring the substation 974, it will be necessary that negative current be supplied over the terminal 28 to the *a* side of the party line in order to operate the ringer at this substation connected to this side of the line and responsive only to negative current. That in order to operate the ringer at the substation 976, it will be necessary that positive current be supplied to this same side of the line, since the ringer at this substation is connected with this side of the line and is operated only by positive current. On the other hand it will be observed that to operate the ringer at the substation 975, negative current must be supplied over the terminal 28 to the *b* side of the line, since the ringer at this substation is connected to this side of the line and is operated only by negative current, and in order to operate the ringer at the substation 977, positive current must be supplied to the same side of the line, since this ringer is connected to this side of the line and is responsive only to positive current. It will be apparent, therefore, as is readily shown upon the drawings, that in two of the sets of connections shown associated with this party line, the *a* and *b* sides of the line are transposed so that in the upper two connections as shown the *a* side of the line is connected to the terminal 28 and in the lower two connections as shown the *b* side of the line is connected to the terminal 28.

It will be furthermore observed that each of the substations of the party line has its own number and that to connect with such a substation, the final selector switch selects terminals designated by such number and connects therewith if the line is idle. Assuming, therefore, that the call which we have already considered was for the substation of a party line and that when the brushes of the final selector rested upon the terminals indicated by the keys depressed by the operator, the selected brushes rested upon the first set of terminals, that is, the uppermost, of the party line 973 shown on Fig. 10. Assuming also that the line was idle, as the final sequence switch passed through its sixth position, a circuit is established from the middle point of the battery 99, through the right winding of the double wound marginal test relay 945, sequence switch contact 912, polarized test relay 946, test brush 25, contact terminal 29, one of the test conductors of the party line, winding 982 of what may be called the negative cut-

off relay of such party line to the negative or free pole of the battery 99 to the middle point of which, it will be recalled, the right winding of the relay 945 was connected. A 5 circuit will therefore be established energized by the full negative portion of this battery and the marginal test relay 945 will attract its armature. The polarized test relay will not operate, since it normally rests in the position to which it would be moved 10 by negative current and is only operated from such position by positive current. Furthermore the negative cutoff relay is not immediately operated, but is operated very shortly thereafter, as will be described. The 15 attraction of its armature by the test relay 945 has closed the circuit hereinbefore traced for the test relay 949, which, by the attraction of its armature in addition to the other circuits which it controls, closes a substitute test circuit including the left winding of the marginal test relay 945 and the winding 982 of the negative cutoff relay, such left winding of the marginal test relay 945 20 being of comparatively low resistance and providing a shunt around the polarized test relay 946 and the right winding of the relay 945. As soon as this low resistance circuit is closed, sufficient current will pass through 25 the winding 982 to cause the negative cutoff relay to be energized and also this low resistance circuit will reduce to such an extent the potential upon the negative test conductor of this party line at all of the sets of 30 terminals in which it appears, that the party line will test busy at such sets of terminals. The remaining operations of the final selector under the circumstances assumed will be the same as hereinbefore described in 35 connection with an ordinary subscriber's line with the exception that in the twelfth position of the final sequence switch, which it will be recalled is the ringing position, when the circuit is again established 40 45 through the polarized test relay 946 by the closure of the sequence switch contact 924, this relay 946 will not be moved from its normal position and negative current therefore will be supplied to the contact terminal 50 55 58 and thence over the *a* side of the party line to the substation 974 where it will cause the operation of the signaling device to signal the subscriber thereat.

In order, however, that the party line 55 may be caused to test busy at the sets of terminals in which it appears other than those at which the test conductor with which the test brush 25 is in contact appears, the energization of the negative cutoff 60 relay has closed a circuit through its armature 990 and the contact device 991, which includes the positive portion of the battery 99, the two windings 985 and 986 of the positive cutoff relay differentially and 65 the contact devices 994. It may be observed

that the local windings 983 and 986 of the negative and positive relays respectively are of relatively low resistance compared with the windings 982 and 985 of such relays. Since, however, as will be recalled was the 70 case with the negative cut-off relay, these relays are marginal, the closure of the local circuit through the two windings of the positive cut-off relay differentially will not sufficiently energize this relay to cause it to 75 attract its armatures, but such circuit, including as it does the low resistance winding 986, will so reduce the potential upon what may be called the positive test conductor of this party line at all of the sets of 8 terminals upon the final selectors in which it appears, that this party line will test busy at all such points.

It will be further observed that the energization of the negative cut-off relays and 8 the consequent attraction of its armatures has opened the connection of the line conductors *a* and *b* to ground and battery, such ground connection including the line relay 988 as is required and as is usual in 9 standard practice. It will therefore be apparent that this party line will now test busy at all of the sets of terminals by which it appears in the various final selectors, both those including test terminals associated with the negative test conductor thereof and those including test terminals connected with the positive conductor thereof, and that such busy condition will exist until the final sequence switch passes into its fourteenth position.

Assuming that the brushes of the final selector when they come in contact with the desired set of terminals had rested upon a set of terminals associated with the last or lowermost connection indicated upon the party line on Fig. 10, in the sixth position of the final sequence switch the test circuit would have received current from the positive portion of the battery 99 through the winding 985 of the positive cut-off relay and again when in its twelfth position the positive current would again pass through the test circuit and the polarized test relay 946 would move its armatures in a clockwise direction to impress positive current upon the terminal 28 and thence over the *b* conductor of the party line to the substation 977 where it would operate the ringer to signal the subscriber thereat. In this case the closure of the low resistance circuit through the left winding of the marginal test relay 945 has, as before, placed a test guard upon the test terminal of all the sets of terminals of this party line in which the positive test conductor appears and has, by the operation of the positive cut-off relay and the closure through its armature 992 and contact device 994 of the local circuit through the two windings of the negative

cut-off relay differentially placed a test guard upon the test terminal of all the sets of terminals of this party line in which the negative test conductor appears.

If in either case when the brushes of the final selector rest upon a set of terminals of the party line and such party line is at that time busy, one or the other of the cut-off relays will be energized so that upon all of its test terminals upon the final selectors a reduced potential will exist and consequently, as the final sequence switch passes through its sixth and seventh positions, the marginal test relay 945 will not be energized. If this set of busy selected terminals is one of the sets of such party line in which the test terminal is connected to the positive test conductor, that is, the one leading through the winding 985 of the positive cut-off relay to the positive or grounded pole of the battery 99, the operation of the final selector from this point on, that is, from the seventh position of the final sequence switch, and the restoration of the final selector, the flashing of the signal 157 and all other operations thereafter take place as after the attempted seizure of a busy ordinary subscriber's line.

It should be particularly noted, however, that in all instances, the next succeeding set of terminals after each set of terminals of a partly line, the test terminal 29 of which is connected to the negative test conductor of such party line, must be a set in which the test terminal 29 is connected to the positive pole of the battery 99. This succeeding set of terminals may be the terminals of an ordinary subscriber's line, a set of terminals individual to one of the stations of a party line in which the test terminal 29 is connected to the positive test conductor of such party line or a dead set of terminals, the test terminal 29 of which is connected to ground through a resistance as plainly shown on Fig. 10 of the drawings. This arrangement is necessary for the reason that when the final selector apparatus tests a set of terminals of a partly line, the test terminal of which set is connected to the negative or free pole of the battery 99, and finds such line busy, the operation of the final selector apparatus will be precisely similar to the operation of such apparatus when it tested the last of a group of private branch exchange trunk lines and found such line busy, as has been hereinbefore described. That is to say, when the final sequence switch comes into its eighth position, the marginal test relay remaining unenergized, no circuit will exist to drive the sequence switch out of its eighth position since the test relay 949 is unenergized and the armatures of the polarized test relay 946 remain in their normal position. A circuit will therefore be established in the eighth position of

the final sequence switch for the power magnet 62 of the brush carriage through the sequence switch contact 917, the back contact and armature of the relay 945, the sequence switch contact 918 and the normal contact 70 and armature 948 of the relay 946. The switch carriage will thereupon move and bring the selected brushes into contact with the next set of terminals where, since positive current is now passed through the polarized test relay 946, such relay will move its armatures, opening the circuit of the power magnet 62 and closing a circuit for the sequence switch through the armature 948 and its alternate contact and the sequence switch contact 922 driving the sequence switch into its eleventh position where the restoration of the final selector to normal, the flashing of the signal 157 and all succeeding operations will take place as 75 has been fully described hereinbefore. This operation of the final selector apparatus will take place whether the line connected to the succeeding set of terminals is busy or idle for the same reasons as set forth in the description of the similar operations in the attempted seizure of the last of a group of private branch exchange trunk lines. 80

It has already been described how the party line will be rendered busy when it is 95 already in use at some other final selector. If, on the other hand, this party line is busy because one of the stations thereof is calling, a plug, such as the plug 141 (see Fig. 1), will have been inserted into the 100 jack 998 of the party line responsive to the calling signal operated by the line relay 988 controlled from the calling substation. As soon as this plug is inserted in the jack 998, a circuit will be established from the middle 105 or neutral point of the battery 99 through the cord relay 142, sleeve contact of the plug 141, sleeve of the jack 998, positive test conductor of the party line 973, winding 985 of the positive cutoff relay and to 110 ground. Current from the positive portion of the battery 99 will thereupon flow through the cord relay 142 with results as hereinbefore described and through the winding 985 of the positive cutoff relay, 115 energizing it and causing it by the attraction of its armatures to cut off the battery and ground connections from the calling party line and to close the local circuit through the negative cutoff relay which includes the 120 negative portion of the battery 99 and the windings 982 and 983 of the negative cutoff relay differentially. It will now be observed that a reduced potential will exist upon all the test terminals of this party 125 line, the potential of those terminals associated with the positive test conductor being reduced by the existence of the connection to the middle or neutral point of the battery 99 through the cord relay 142 and on 130

those associated with the negative test conductor by the connection to the middle or neutral point of the battery 99 through the winding 983 of the negative cutoff relay and 5 the armature 992 and contact device 994 of the positive cutoff relay.

It is apparent, therefore, that whenever a plug 141, or the brushes of the final selector select and make contact with a set of 10 terminals connected with a party line, that the electrical condition of all of the sets of terminals associated with such line will be so modified that the line will test busy to any other final selector apparatus attempting 15 to make connection therewith precisely as has been hereinbefore described in connection with ordinary subscribers' lines and private branch exchange trunk lines. Furthermore, that such final selector upon 20 bringing its selected brushes into contact with a set of terminals of a party line will, if such line is idle, automatically and without any further act on the part of the calling subscriber or the operator, select and 25 signal the particular substation desired to the exclusion of all others, while on the other hand if such line is busy it will automatically and unfailingly accomplish the flashing of the signal 157 indicating that the 30 line is busy. It may also be noted that in all cases throughout the attempted seizure of a busy party line, as is also the case throughout the attempted seizure of one of a group of busy private branch exchange 35 trunk lines, the selected brushes 23 and 24 are dead and no interference with busy lines can result.

Selection controlling without translation.—The case has been assumed that connection was desired by the calling subscriber with a line terminating in an exchange of but five hundred lines, the arrangement of the terminals of which lines on the groups of final selectors was two hundred 40 of such lines to a group. In this case it was necessary that the selection controlling operations involved translation, that is to say, that the designation of the line desired impressed upon the keys arranged according to the decimal system of notation, should readily and accurately control the 45 selection of the desired line in an exchange in which the group of lines and the selection thereof is in accordance with some other system of notation than the decimal system. It has been explained how this translation was accomplished, the particular means embodied in this form of my invention involving the use of registers interposed between 50 the keys and the counting relays, and it has also been shown how such registers, coöperating with the counting relays or sender proper controlled necessary selecting operations.

60 65 It will now be assumed that the calling

subscriber, whose substation is shown at the left of Fig. 1 of the drawings, desires connection with a line in an exchange in which the lines terminating therein are arranged upon final selectors having a capacity of one hundred lines each; their arrangement on such final selectors and the arrangement of the trunk selectors leading to such final selectors is according to what is known as the straight decimal system. That is to say, in an exchange of ten thousand lines, there will be one hundred groups of final switches, each of such groups carrying the terminals in multiple of one hundred of such lines, the first bank of sets of terminals of each such final selector carrying the sets of terminals 0 to 9 of the particular hundred to which the selector is individual, the second bank carrying the sets of terminals 10 to 19 of the particular hundred to which the switch is individual, the third bank carrying the sets of terminals 20 to 29 of the particular hundred to which the switch is individual, and so on. Furthermore such exchange embodies groups of hundreds selectors adapted to select an idle trunk line leading to and connected to a final switch carrying the terminals of the lines of the desired hundred lines and also includes groups of thousands selectors designed to select an idle trunk line leading to and connected to a hundreds selector through which connection can be made to the desired line. This arrangement of thousands, hundreds and final selectors is well known and comprises what is generally known as the straight decimal system of selection. In an exchange of this character, the number of switches of each kind is determined by the maximum traffic which the exchange will have to carry, but since this arrangement of switches is also well known and is designated as the percentage system, it need not be further described herein. It should be also observed that in the exchange through which connection has been hereinbefore traced, the switches were also limited in their number by the maximum traffic which the exchange was designed to carry, that is to say, both such exchanges are arranged upon what is known as the percentage basis.

Assuming, therefore, that the calling subscriber desires connection with a line in such an exchange in which the lines are arranged according to the decimal system and that to obtain such line no translation is necessary. Such an exchange is represented by the third or No. 2 office key 424 upon Fig. 4 of the drawing. Furthermore assuming that the designation of the particular line desired is No. 3752. As soon as the operator receives a signal from the calling subscriber, she will insert the plug 141 into the jack 81 of such subscriber and the various operations of the district selector apparatus, the listening-in

apparatus, the cord finder apparatus and the sender apparatus will take place precisely as has been hereinbefore described up to the point where the operator, having learned the designation of the desired line, depresses the office key individual to the particular exchange through which connection is desired. Having received the necessary information, the operator depresses the third or No. 2 office key 424 and the district and office registers come into their set positions precisely as has been hereinbefore described, in which positions, however, in this instance, the contact devices indicated as closed in the third or No. 2 position of such registers are closed instead of the ones hereinbefore referred to. It may be pointed out at this time that in this position of the office register sequence switch the contact devices 618 and 619 are open as well as the contact device 620, but in such position in addition to the contact device 603, contact devices 632 and 602 are closed.

District and office selection will now take place precisely as has been hereinbefore described—in this instance of course the district selectors choosing the terminals of an idle trunk line from the third bank of sets of terminals thereon and the office selector choosing the terminals of an idle trunk line in the third bank of sets of terminals thereon, so that an interoffice or two-wire trunk has been selected to the No. 2 office, that is, the third office in the third district. The closure of the contact devices 632, 602 is without effect in office and district selection, but the purpose of their closure will hereinafter appear. The operator has in the meantime depressed the numerical keys indicating the designation of the desired line. She has depressed the fourth or No. 3 thousands key 425, the eighth or No. 7 hundreds key 426, the sixth or No. 5 tens key 427 and the third or No. 2 units key 428.

It will be obvious that in an exchange of the character at present assumed, an additional selector switch will be required of the character hereinbefore described as the group switch shown on the drawings in Fig. 8. The operation of this additional switch, however, is precisely akin to the operation of the group switch, which may now be considered the hundreds switch, and in consequence, to prevent a multiplication of drawings and the confusion incident to the rearrangement thereof, no such additional switch is shown.

It will be recalled that when selection in the office selector had been completed, the operator's equipment comprising the sender and cord finder apparatus, took up the further selection controlling operations necessary for the selection of the desired line, provided the numerical registers had reached their set positions in response to the depre-

sion of the numerical keys. If these registers had not at this time reached their set positions, it will be recalled that the sender apparatus awaited such completion, and that at this time the various sequence switches were in the following positions: District sequence switch in its sixth position. Listening sequence switch in its fifth or eighth position. Cord finder sequence switch between the sixth and fifteenth positions. The sender sequence switch in its sixth position and the office sequence switch in its thirteenth position.

When the cord finder sequence switch passes out of its ninth position, the operators' keys are released, as has been hereinbefore described. The apparatus is now ready to take up further selection controlling operations and, therefore, upon the coming of the cord finder sequence switch 222 into its tenth position, a circuit is established for the sender sequence switch 336 through the sequence switch contacts 307 and 211 and front contact and armature of the test relay 229. The sender sequence switch 336 now moves into its seventh position and comes to rest therein, the contact device 619 upon the office register, which in the former case assumed caused the sender sequence switch to continue its movement through its seventh and eighth positions, being opened in the third or No. 2 position of such register, in which position the register now is. The sender sequence switch therefore rests in its seventh position while the thousands selection controlling operation takes place in the operator's equipment and while thousands selection is correspondingly taking place in the thousands selector. This operation, as has been before noted, is precisely similar to the operation which took place in the group selector hereinbefore described with the exception that it takes place in the seventh position of the sender sequence switch rather than in the ninth position as was described. Upon the completion of the thousands selection, which has selected the fourth set of brushes, the sender sequence switch is driven into its ninth position, preparing the operator's equipment for the hundreds selection controlling operation, while in the meanwhile the thousands selector is searching for and seizing an idle trunk line leading to a hundreds selector of the fourth or No. 3 thousand lines of the exchange in the bank of sets of terminals associated with the selected brushes upon such thousands selector.

As soon as the fundamental circuit has been completed to the hundreds selector, hundreds selection takes place in a manner fully set forth to cause the release of the desired set of brushes upon the hundreds selector—in this instance the eighth set corresponding to the eighth or No. 7 hundred

of the selected thousand lines of the exchange and upon the completion of the selection of this set of brushes upon the hundreds selector the sender sequence switch 336 will be driven into its eleventh position, preparing the operator's equipment for the tens selection controlling operation, while in the meanwhile the hundreds selector is searching for and seizing an idle trunk line 5 leading to a final selector in the bank of sets of terminals associated with the selected brushes of such hundred selector. In view 10 of the fact that in connection with this hundreds selection the contact device 632 upon the office register is closed and the contact device 618 thereon is open, it will be necessary to intermittently energize and deenergize the stepping relay 701 eight times before selection will be stopped by the opening 15 of the fundamental circuit, since in this case the circuit for the cut-off relays 719 will pass through the contact device 607 upon the hundreds register and the contact device 632 upon the office register rather than as was hereinbefore described in connection 20 with group selection. Therefore, it will be obvious that when the armature 702 of the stepping relay 701 retracts for the eighth time during this selection in order 25 to close the circuit for the counting relay 713 associated with and connected to the contact device 607 upon the hundreds register, the tripping spindle of the hundreds selector will be coming into its eighth position, that is to say, in the position to trip and release the eighth set of brushes upon such selector. The tripping spindle will, therefore, come to rest in its eighth position and upon the movement of the hundreds selector switch carriage, the eighth set of brushes will be released and proceed to select an idle trunk line in the eighth bank of terminals on such selector, that is, a trunk line to the eighth group of final 30 selectors, which is the group individual to the No. 7 hundred lines, of the particular thousand lines in the exchange.

When the sender sequence switch comes into its eleventh position and the hundreds selector has seized an idle trunk line to one of the desired group of final selectors, the fundamental circuit will be established between such final selector and the operator's equipment in a manner precisely as hereinbefore described, and tens selection will now take place. This selection is accomplished precisely as has been hereinbefore described and need not be recited again in detail. Upon the completion of tens selection, units selection takes place with the sender sequence switch 336 in its thirteenth position and the final sequence switch in its fifth position, precisely as has been hereinbefore described, it being only necessary to note that 55 the closure, at this time, of the contact de-

vice 602 upon the office register assures that units selection will be controlled by the first ten contact devices counting down from the top of Fig. 5, regardless of whether the contact device 628 or 625 upon the hundreds 70 register is closed. In the particular case assumed upon the third alternate energization and deenergization of the stepping relay 701, the circuit will be closed for the cut-off relays 719 through the contact device 609 75 and the contact device 602 and the final selector will be brought to a stop with the released brushes thereof in contact with the third set of terminals upon the particular bank with which they coöperate. Upon the completion of this selecting operation the fundamental circuit is opened, as has been fully described, the sender sequence switch 336 moves out of its thirteenth position and the final sequence switch moves out of its 80 fifth position, and from this point on all of the operations of the restoration of the operator's equipment and of the testing and ringing of the desired line, the completion of the talking connection between the two 85 substations, the restoration of the entire apparatus and all other operations of the selectors and their associated apparatus take place precisely as has been hereinbefore 90 fully described. 95

Connection to manual exchange.—Assuming that the calling subscriber, when he has obtained conversational connection with the operator, informs her that he desires connection with a line terminating in an ordinary manual exchange. In this case all that is necessary is the selection of an idle trunk line leading to such exchange. It has been assumed furthermore for the purpose of illustration that it is desirable that it should 100 be necessary only to select an idle trunk line leading from the district selector and in the operation to be described, therefore, all selection controlling operations and their corresponding selections, except the district selection controlling operation and district selection will be eliminated. It will be assumed that the manual exchange referred to is the No. 0 exchange. The operator will, therefore, depress the No. 0 office key 432 105 and when the district and office registers have come into their set positions, district selection will take place, as has been hereinbefore fully described, such selection taking place in the third position of the sender 110 sequence switch 336. When the sender sequence switch, however, leaves its third position at the completion of district selection, it closes in its fourth position and will maintain closed in its fifth position the sequence switch contact 308, thereby establishing a circuit for the district sequence switch 101, which may be traced from battery through such sequence switch, sequence switch contact 107, conductor 248, contact terminal 115 120 125 130

236 upon the cord finder, cord finder brush 231, conductor 237, sequence switch contact 308, conductor 631, district register contact device 630, conductor 299, conductor 245, 5 cord finder brush 232, contact terminal 237, conductor 115, sequence switch contact 110, back contact and armature 147 of the restoring relay 146 to ground and back to battery. This circuit will be closed in both the second and sixth positions of the district sequence switch and therefore, when such sequence switch comes into its sixth position, upon the seizure of an idle trunk line leading to the desired manual office, the trunk lines to 10 which are connected to the sets of terminals which appear in the bank of terminals co-operating with the first or No. 0 set of selector brushes upon the district selector, the district sequence switch will continue in motion. Upon leaving its sixth position, the 15 district sequence switch will open the circuit traced; but also opens at the same time at the sequence switch contact 110 the circuit for the test relay 229 and the reset relay 332, so that the entire operator's sending equipment will be immediately restored to normal. The retraction of the armature 228 of the test relay 229 closes a circuit for the 20 cord finder sequence switch 222 through the sequence switch contact 206, which will be maintained through the eighteenth position of such sequence switch, thereby driving it into its normal position. The retraction of the armature 334 closes a circuit for the 25 sender sequence switch 336 through the sequence switch contact 303, which will be maintained continuously through the eighteenth position of the sender sequence switch, thereby returning it to normal. In this way 30 all of the apparatus of the operator's sending equipment, which has been used in connection with this call, will be restored to normal. It will be observed that when the district sequence switch left its sixth position, at which time it opened the circuit for 35 the test relay 229 and the reset relay 332, it opened the sequence switch contacts 122 and 123, so that in no way possible could the immediate restoration of the sender and 0 cord finder apparatus after district selection affect further the apparatus of the district selector, nor any apparatus associated with the selected trunk line at the manual exchange.

5 The district sequence switch, however, when it left its sixth position, did not come to rest in its seventh position, finding in such position a circuit for itself established through the sequence switch contact 119, 0 front contact and armature of the test relay 152, sequence switch contact 121, back contact and armature 147 of the restoring relay 146. The sequence switch therefore continued in its movement and came to rest in its 5 eighth position. The further operations of

the district selector apparatus will proceed precisely as has been hereinbefore described, the closure of the trunk circuit including battery at the manual office, moving the district sequence switch into its ninth position, 70 and the clearing of the trunk circuit of battery at the time when conversation is to begin, moving it into its tenth position. Furthermore the energizing of the district line relay 150 in the tenth position of the sequence switch lighting the signal lamp 157 and the lighting of the signal lamp 156 will indicate to the operator that restoration is desired and the removal of the plug 141 will produce restoration of the district selector apparatus precisely as has been hereinbefore described, no energizing circuit existing for the district line relay 150 when the district sequence switch comes into its fourteenth and fifteenth positions. 85

Restoration before selection completed.—If at any time before selection has been completed the operator should desire to restore the apparatus to normal for any reason, for example, assuming that she has by accident 90 in indicating the designation of the desired line improperly depressed one or more keys, she may accomplish this restoration immediately and without removing the plug 141 from the jack of the calling line by depressing her master wipe out key 199 (see Fig. 6) while the listening sequence switch 176 individual to the particular cord circuit in use is in its fifth position. It will be remembered that selection began while 95 the district sequence switch was in its second position and was completed before such sequence switch left its sixth position. If, therefore, during selection the master wipe out key 199 should be depressed, the listening sequence switch 176 being in its fifth position, a circuit would be established from battery through the restoring relay 146, sequence switch contact 105, listening sequence switch contact 188, master wipe out key 199 100 to ground and back to battery. The restoring relay 146 will thereupon be energized 105 and will attract its armatures 147, 148 and 149. The attraction of the armature 148 closes a locking circuit for the restoring relay 146 through the sequence switch contact 134, which will be maintained through the tenth position of the district sequence switch, the attraction of the armature 147 110 of the restoring relay 146 closing a circuit for the district sequence switch 101 through the sequence switch contact 135, which will be closed in the second, third, sixth, eighth, ninth and tenth positions of the sequence switch, as is fully indicated upon the drawing. 115

If the master wipe out key is operated while the district sequence switch is still in its second or third positions, that is, if the selector switch carriage is still in its normal position, when the district sequence switch 120 125

- reaches its fourth position, it will find a circuit for itself through the front contact and armature of the test relay 152 and the sequence switch contact 121, as has been hereinbefore described, which will move it on into its sixth position. The circuit for the test relay 152 by the energization of which this movement is accomplished will extend through the spring 52, arm 43 and plate 46, all of the interrupter at the top of the brush carriage, thence through the resistance 155 and the front contact and armature 149 of the restoring relay 146.
- If the district sequence switch, however, is in its fourth position and the switch carriage is moving from its normal position when the energization of the restoring relay 146 takes place, the selection of the idle trunk line will proceed as has been hereinbefore described, but when subsequently in the usual course the district sequence switch comes into its sixth position, it will find an energizing circuit for itself closed through the sequence switch contact 135 and it will leave such sixth position. This same circuit for driving the district sequence switch out of its sixth position will exist if the selector switch carriage had not left its normal position so that in any case upon the energization of the restoring relay 146, the district sequence switch will be driven into its seventh position, which is the restoring position of the switch carriage under the circumstances assumed, if such switch carriage has left its normal position. In this position of the sequence switch a circuit is established for the switch carriage power magnet 62 through the back contact and armature of the test relay 152 and the sequence switch contacts 121 and 118. The switch carriage will therefore move until it comes into its normal position when the circuit through the armature 149 and front contact of the restoring relay 146 and the interrupter plate 46, which circuit has been hereinbefore traced, will energize the test relay 152 to open the circuit of the power magnet 62, close the circuit of the holding magnet 65, stopping the switch carriage in its normal position, and at the same time close a circuit for the district sequence switch to drive it out of its seventh position. The sequence switch, by the closure of the circuit through the sequence switch contact 135 and the front contact and armature 147 of the restoring relay 146, will continue to move until it reaches its fourteenth position. From this position, since the circuit for the district line relay 150 is destroyed, the restoration of the district selector apparatus will be completed, as has been fully described, the sequence switch not stopping, however, in its seventeenth position in this case, as the switch carriage is already restored to its normal position.

Assuming that the master wipe out key was depressed after the district sequence switch had left its third position and the trunk line to an idle office selector had been seized, the attraction of the armature 147 in the fifth or sixth position of the district sequence switch, would have caused the deenergization of the office restoring relay 823 and the restoration of the office selector apparatus, if it had left its normal position, will proceed simultaneously with the restoration of the district selector apparatus as hereinbefore described. This restoration, consequent upon the deenergization of the office restoring relay 823, will take place as 80 has been hereinbefore described if the office sequence switch 801 has left its third position, or if it has just come into its third position restoration will proceed as soon as, upon the seizure of an idle trunk line to a 85 group selector, the office sequence switch leaves its third position.

If, however, the deenergization of the office restoring relay 823 takes place before the switch carriage had left its normal position, that is, while the office sequence switch was still in its second position, an energizing circuit would have been immediately established for the test relay 831 from battery through the armature 822 and its back contact of the office restoring relay 823, resistance 830, plate 46, arm 43 and spring 52 of the interrupter at the top of the switch carriage, test relay 831, sequence switch contact 811 to ground and back to battery. The 100 energization of the test relay 831 consequent upon the closure of this circuit will close through the front contact of its armature a circuit for the sequence switch, which will drive such sequence switch out of its third position when the deenergization of the office line relay 821, upon the opening of the fundamental circuit, the office sequence moves the switch 801 out of its second position. The energization of the test relay 831 110 has also prevented by the opening of the circuit through the back contact of its armature any movement of the selector switch carriage. The office sequence switch upon reaching its thirteenth position, under the 11 control of its special sequence switch contact 802, will find a circuit established for itself through the sequence switch contact 810 and back contact and armature 824 of the office restoring relay 823. Upon reaching its sixteenth position, the carriage having been already restored, the test relay 831 will be again energized through the circuit traced through the armature 822 of the office restoring relay 823 and the sequence 12 switch contact 811, and a circuit will be established for the office sequence switch to drive it out of its sixteenth and into its normal position. The entire office selector apparatus is now in its normal condition, the 13

sequence switch contact 806 being again closed so that the trunk leading to this particular selector apparatus may be seized by a hunting district selector.

5 If, when the operator depressed the master wipe out key, a final selector had been seized, it is necessary that such selector and its associated apparatus be restored to its normal condition. When the district sequence switch, therefore, came into its seventh position, it opened the trunk circuit so that the final line relay 941 is immediately deenergized. Assuming that the final selector carriage has not yet left its normal 15 position, that is, the final sequence switch is still in its second position, restoration will take place as follows: a circuit is established for the final sequence switch 901 through the sequence switch contact 909 20 and the armature 960 and back contact of the battery control relay 943 and the back contact and armature of the final line relay 941. This circuit will also be maintained in the fifth position of the final sequence 25 switch, since no reenergization of the final line relay can now take place, the brushes of the district selector having left the terminals of the trunk line and the trunk line is therefore open. The final sequence switch 30 upon leaving its fifth position will move into its eighth position, in which position a circuit will be established for the marginal test relay 945 from the middle or neutral point of the battery 99 through the right 35 winding of such relay, sequence switch contact 913, plate 46 and arm 43 of the interrupter at the top of the switch carriage to ground through the frame of the switch carriage. The closure of this circuit will 40 cause the energization of the marginal test relay 945 which, by the attraction of its armature, establishes a circuit for the test relay 949 through the sequence switch contact 918 and the normal contact and armature 948 45 of the polarized test relay 946. The test relay 949 will therefore be energized and will, by the closure of the circuit through the sequence switch contact 922 and front contact of its armature 952, drive the sequence 50 switch out of its eighth position and into its eleventh position. In this position the circuits just traced will be again established with the exception that the energizing circuit for the test relay 949 will at this time 55 pass through the sequence switch contact 914 and directly to ground rather than through the sequence switch contact 918 as heretofore.

The sequence switch will move out of its 60 eleventh position and will find prepared for itself in the twelfth and thirteenth positions a circuit through the sequence switch contact 925, the plate 46 and arm 43 of the interrupter to ground through the frame of the 65 switch carriage. In the fourteenth posi-

tion of the sequence switch at the time when the circuit is interrupted for the battery control relay by the interrupter 963, both such battery control relay and the final line relay 941 will be deenergized and the final 70 restoring relay will be energized in a manner hereinbefore described and attract its armature, closing a circuit for the final sequence switch 901 and drive it out of its fourteenth position. The final sequence 75 switch upon coming into its sixteenth position will find a circuit prepared for itself through the sequence switch contact 922 and the front contact and armature 952 of the test relay 949, which is maintained energized 80 in the sixteenth and seventeenth positions of the sequence switch by the energization of the marginal test relay 945 by the circuit hereinbefore traced through the sequence switch contact 913 and the interrupter at 85 the top of the switch carriage to ground. The final sequence switch will therefore move into its first or normal position, all of the final selector apparatus now having been entirely restored to its normal condition. 90

It has been explained how the restoration of the final selector will take place upon the depression of the master wipe out key when this takes before the final selector switch 95 carriage has left its normal condition. Assuming, however, that this key is not depressed until this switch carriage has started in its movement for units selection. Immediately upon the opening of the trunk 100 circuit, as the district sequence switch leaves its sixth position, the final line relay 941 is deenergized (subject to the usual centering action of the shunt circuit through the sequence switch contact 907 and the interrupter 105) and the circuit for the power magnet 62 will be opened and the circuit for the holding magnet 65 be closed to stop the switch carriage, while at the same time, a circuit will be closed for the final sequence 110 switch through the sequence switch contact 909. The final sequence switch will now move into its eighth position, testing the line with which the brushes chance to be in contact precisely as in normal selection. If the 115 line with the terminals of which the brushes are now in contact is one in which the test conductor is charged with a positive potential, the polarized test relay 946 will, in the eighth position of the sequence switch, maintain its armatures shifted in a clockwise direction as hereinbefore described and the circuit through the sequence switch contact 922 and the alternate contact and armature 948 of such polarized test relay will drive 120 the sequence switch into its eleventh position. If, on the other hand, the test conductor of the line with the terminals of which the brushes are now in contact has negative potential thereon, and if such line 125 130

is idle, the marginal test relay 945 will be energized and the test relay 949 will be energized and locked up as has been hereinbefore described. A circuit in this case will be established for the final sequence switch 5 through the sequence switch contact 922 and the front contact and armature 952 of the test relay 949, and such sequence switch will move into its eleventh position. If, however, such line, with its test conductor having negative potential thereon, is busy, the selector brush carriage will move precisely as in private branch exchange trunk hunting, hereinbefore described, until such brush carriage 10 brings the selected brushes into contact with the terminals of an idle line, or of a line the test conductor of which has positive potential thereon. As soon as this occurs either the test relays 945 and 949 will 15 be energized as hereinbefore described, or the polarized test relay 946 will move its armatures in a clockwise direction, depending upon the character and condition of the line with the terminals of which the brushes 20 are now in contact. In either case one or the other of the circuits just previously traced will be established to drive the sequence switch into its eleventh position.

In the eleventh position of the sequence 30 switch under the circumstances assumed, no circuit will be found to exist, immediately, for the final sequence switch, since the test relay 949, if it has been energized, was unlocked in the tenth position of the sequence switch. This will be the case for the reason 35 that the ground connection through the sequence switch contact, 923, conductor 961 and front contact and armature of the test relay 941, is now open, the final line relay 40 941 being deenergized due to the opening of the trunk circuit at the district selector. The final sequence switch will therefore rest in its eleventh position and the restoration of the selector brush carriage will take place 45 as has been hereinbefore described. Upon the completion of such restoration, the final sequence switch will move into its fourteenth position and thence into its first or normal position under the control of circuits and in 50 a manner hereinbefore described. The entire final selector apparatus is now in its normal condition.

The restoration of the group switch shown in Fig. 8 upon the operation of the master 55 wipe out key is controlled from the originating end of the trunk circuit if the operation of such key takes place before the group sequence switch leaves its seventh position and from the final selector if it takes place 60 after it has left its seventh position. If the group sequence switch has left its seventh position, the restoration under the control of the final sequence switch will take place precisely as has been hereinbefore described 65 in connection with ordinary restoration and

need not be described again in detail. If, however, restoration due to the operation of the wipe out key begins before the group sequence switch has left its seventh position, that is, before it has seized upon terminals 70 of an idle line leading to a final selector, the opening of the trunk circuit at the district selector, which takes place in the seventh and again in the eleventh position of the district sequence switch, will cause the de- 75 energization of the group line relay 871. A circuit will then be closed for the group sequence switch 851 through the sequence switch contact 858 and back contact of the group line relay, which will drive the group 80 sequence switch 851 out of its second position and subsequently out of its seventh position.

Upon coming into its eighth position, the group sequence switch, if the selector carriage 85 has not left its normal position, will establish a circuit from battery through the sequence switch contact 864, resistance 880, plate 46, arm 43, and spring 52 of the interrupter apparatus at the top of the switch 90 carriage, test relay 881, sequence switch contact 861 to ground and back to battery. This circuit will be maintained in the eighth and ninth positions of the group sequence switch and the test relay 881 will be energized to close at the front contact of its armature a circuit for the group sequence switch 851, which will drive such sequence switch into its fourteenth position, the movement of the sequence switch through its 95 ninth to thirteenth positions being under the control of its special contact 852.

Upon coming into its fourteenth position, the switch carriage being in its normal position, the circuit will be reestablished 105 through the sequence switch contact 864 and the test relay 881 and the group sequence switch will be driven into its sixteenth position, where the same circuits being again established, the group sequence switch will 110 again come into its normal position. It may be here observed that at any time after the switch carriage of the group selector has left its normal position, that is, during or subsequent to the seventh position of the 115 group sequence switch 851, the operations of the group selector apparatus are under the control of local circuits until such time as the group selector has made contact with and seized an idle trunk line leading to a 120 final selector, so that from the stage in which control of restoration from the originating end of the trunk circuit is destroyed, the apparatus will be driven to the stage in which restoration will be under the control 125 of the final selector apparatus. The operations of the group selector apparatus will take place automatically and unerringly so that under no possible circumstances can the apparatus of this selector, any more than 130

the apparatus of any other selector, be stopped or stalled in an off-normal position.

Restoration when called party does not answer.—If, when selection is complete and the called party is being rung, such party

5 does not respond, the operator will, after a proper interval, restore the apparatus to normal. Under these circumstances, it will be recalled that the district sequence switch 10 is in its ninth position and the final sequence switch in its twelfth position, these positions being the ringing positions of the respective apparatus. To produce this restoration, the

15 operator removes the plug 141 from the jack 81 of the calling subscriber, and de-presses the master listening-out key 198.

The removal of the plug 141 from the jack 81 causes the deenergization of the cord relay 142, which allows its armatures to re-20 turn to their retracted positions. On the

25 depression of the master listening-out key 198, the energizing circuit for the listening sequence switch 176 is closed from battery, through the winding of the sequence switch

magnet, sequence switch contact 190, master 30 listening-out key 198, to ground and back to battery. The listening sequence switch 176 moves, therefore, from its fifth position into its eighth position, closing in

35 its eighth position the sequence switch contact 191, and keeping closed the energizing circuit for the listening sequence switch through the armature and back contact 144 of the cord relay 142, and the lis-40 tening sequence switch 176 moves from its eighth into its first position. On arrival at

its first position the listening sequence switch 176 closes the sequence switch contacts 178 and 179, closing in this position

45 an energizing circuit for the district sequence switch 101, which may be traced from battery, through the energizing winding of the district sequence switch magnet, sequence switch contact 185, sequence switch

50 contact 179, armature and back contact 144 of the cord relay 142, to ground and back to battery. The closure of this circuit will cause the district sequence switch to move from its ninth through its tenth and into

55 its fourteenth position. When the district sequence switch moves out of its tenth position the energizing circuit for the final line relay 941 is opened and such relay, in allowing its armature to retract, closes the circuit to the final restoring relay 956, as hereinbefore described, resulting in the movement of the final sequence switch into its fourteenth position. In this position at the

60 interval when the battery control relay 943 and the final line relay 941 are both en-55 ergized or both deenergized, the final restoring relay 956 will be again energized or maintained energized and the final sequence switch consequently will be driven out of its

65 fourteenth position and into its sixteenth

position. From this point on, the restoration of the entire apparatus will take place precisely as has been hereinbefore described in connection with restoration after a successful call.

70 It will be observed that in all modes of restoration the tripping spindle of each of the various selectors will be restored to its normal position when the associated sequence switches reach the appropriate positions to 75 energize the tripping spindle power magnet 68 through the interrupter contacts 59 associated with such power magnet and its tripping spindle.

Master listening-out key.—The purpose of 80 the master listening-out key 198 is to enable the operator to conveniently remove her telephone set from conversational connection with any cord circuit of her position with

which at that time it may be associated. The depression of the master listening-out key 198 will establish a circuit for the listening sequence switch 176 through the sequence switch contact 190. It will be obvious from

85 the arrangement of sequence switch contacts shown that the listening sequence switch associated with but one cord will be in its fifth position at any one time, and consequently the operator's telephone set 192 can be in conversational connection with but one cord 90

at any one time. On the other hand it will be observed that any number of listening sequence switches may simultaneously be in their first and normal positions or in their eighth positions or off-listening positions. 95

It will be observed that the depression of the master listening-out key has the same effect upon the listening sequence switch 176, which is in its fifth position, as the insertion of the plug of some other cord circuit into 100

the jack of a calling line.

105

Master flash back key.—The master flash back key shown at 196 on Fig. 6 is for the purpose of enabling the operator to include

battery across the trunk line when the district sequence switch is in its ninth and tenth positions and the listening sequence switch is in its fifth position in order to signal over

110 a trunk line extending to a manual office. The circuit for including this battery across the trunk line may be traced from one side of the trunk line through district sequence switch contact 128, the listening sequence switch contact 188, one side of the master

115 flash back key 196 through the battery and thence by the other side of the master flash back key 196 through the listening sequence switch contact 189, district sequence switch contact 129 to the other side of the trunk line.

120 The bridging of this battery across the trunk line will be without effect at the originating end of the trunk line when the district sequence switch is in its tenth position further than causing the signal lamp 157 to be lighted by the energization of the district 125

130

line relay 150, but the inclusion of such battery will in any desired manner signal the operator at the manual exchange to which the particular selected trunk line leads.

5 *Ring-back apparatus.*—If, for any reason, the operator should desire to signal the calling party, for example, when he has replaced his receiver upon the hook after having informed the operator of the desired call, she 10 may do so by depressing her ring-back key 193, provided the listening sequence switch associated with the cord connected to the subscriber's substation through the plug 141 and jack 81 is in its fifth position. A circuit 15 will then be established from the source of ringing current 194 through the alternate contact of the upper spring of the ring-back key 193, sequence switch contact 184, tip contact of the plug 141, tip spring of the jack 20 81, out over the subscriber's line and through his ringer shown at the substation 91, through the condenser thereat and back to the ring spring of the jack 81, through the ring contact of the plug 141, supervisory relay 145, sequence switch contact 185, lower 25 spring of the ring back key 193 and through the alternate contact thereof back to the source of ringing current. The operator will in this way be enabled to recall the calling 30 subscriber to the telephone when the call, for example a toll call, has been completed. It will be recalled, furthermore, in this connection that the operator may replace her telephone set in operative association with 35 any cord by depressing the individual listening-in key 197 associated with such cord.

40 *Progression signals.*—In addition to the supervisory signal lamps 156 and 157, the operations and functions of which have been hereinbefore described, I provide the signal lamp 158 which may be called the ringing lamp. This lamp is lighted in the second to 45 sixth positions of the district sequence switch by the closure of a circuit for it through the sequence switch contact 110 and back contact and armature 147 of the district restoring relay 146. When the district sequence switch leaves its sixth position, this 50 lamp 158 is extinguished by the opening of the circuit described, but is again lighted when the ninth or ringing position of the district sequence switch is reached through the sequence switch contact 127, the front contact and armature of the district line 55 relay 150 and the sequence switch contact 118. This lamp is again extinguished when the district sequence switch leaves the ninth position due to the opening of the sequence switch contact 127. It will therefore be apparent 60 that the display of this lamp serves to indicate to the operator, first, that the selecting operations are taking place and, subsequently, that the called party is being signaled. By its final extinguishment it 65 serves to indicate that the called party has

answered and that the entire apparatus is now in its talking condition.

A further feature of the system embodying my invention shown herein is the signaling means and apparatus whereby the operator may know at any time at what particular stage in the selecting operations her controlling equipment and the various selector switches are. This signaling apparatus comprises in part a row of lamps 351, 75 352, 353, 354, 355 and 356 associated with and individual to the sender and controlled by the sender sequence switch 336. A similar set of lamps is associated with and individual to the sender which is associated 80 with the cord finder sequence switch 272 shown upon the lower right-hand portion of Fig. 2. These lamps 351 to 356 inclusive are controlled by the sequence switch contacts 361, 362, 363, 364, 365 and 366 of 85 the sender sequence switch. As these various sequence switch contacts are closed, they establish circuits from battery through the respective lamps and the lighting of the various lamps therefore depends upon the 90 positions of the sender sequence switch in which such sequence switch contacts are closed.

It will be recalled that the second position of the sender sequence switch is reached 95 only after the cord finder has seized upon the connecting circuit taken for use and therefore the lighting of the lamp 351 due to the closure of the sequence switch contact 361 in the second position of the sender sequence switch serves to indicate to the operator that the sender apparatus is now connected with the cord over which connection will take place. It will be again recalled that district selection takes place in the 10 third position of the sender sequence switch. When, therefore, the lamp 351 has been extinguished and the lamp 352 displayed due to the closure of the sequence switch contact 362 in the third position of the 11 sender sequence switch, the operator will know that district selection is now taking place. Similarly by the display of the lamp 353, the operator will know that office selection is taking place, since office selection takes place in the fifth position of the 12 sender sequence switch such sequence switch having passed through its fourth position without coming to rest. Similarly the lighting of the lamp 354 by the closure of the sequence switch contact 364 will indicate to the operator that the group selecting operation is taking place, or, when connection is being made to an appropriate exchange, that the thousands and hundreds selecting operations are taking place. Likewise the display of the lamp 355, due to the closure of the sequence switch contact 365, will inform her that the tens selection is taking place; and finally the display of the lamp 356, due 13

to the closure of the sequence switch contact 366, will inform her that the final or units selection is taking place. The extinguishment of this last lamp 356 also serves 5 to indicate that the entire selecting operations are complete and that the sender apparatus and cord finder apparatus to which this group of lamps is individual, is being restored to normal, or has reached such 0 condition. By means of these lamps the operator may at a glance inform herself as to the progress of the selection under control. Furthermore if by any mischance selection should be held up at any stage, 5 the continued lighting of one of the signal lamps will immediately inform her at precisely what stage the trouble or delay has occurred.

It will be observed throughout the description of the operation of my invention as shown herein that at all points well established and well known operating standards are maintained.

It will of course be understood that while 5 I have shown, upon the drawings a plurality of batteries or other sources of current, all of such batteries or other sources of current where they are of the same character and potential and located in the same 0 exchange, may be and are preferably one and the same battery or source of current.

Having described my invention, what I desire to claim is:

1. In a telephone exchange system, the combination with an automatic selector including a test contact brush, test conductors terminating in test terminals on said selector, a circuit including said test brush and one of said test terminals, relays in said circuit operating upon their first energization to place a busy test condition upon the test conductor of the included test terminal and upon a subsequent energization to control the restoration of said selector to normal.

2. In a telephone exchange system, the combination with an automatic selector including a test contact brush, of a plurality of test conductors, terminals of which appear on such selector, a conductor connected to said test brush, relays in said conductor, said relays being energized in the movement of said test brush over said terminals to stop said brush in contact with the terminal of an idle test conductor and place 5 a busy test condition upon such conductor, said relays upon a subsequent energization controlling the restoration of said brush to normal position.

3. In a telephone exchange system, the combination with an automatic trunk selecting switch apparatus, of an automatic line selecting switch apparatus, a circuit established in an operated position of said trunk switch apparatus extending between such apparatus, relays at the trunk switch apparatus in said circuit energized upon the closure of said circuit to change the electrical condition of that portion of said circuit at the line switch apparatus, a switching contact rotated at said line switch apparatus 65 operating in the first movement of such apparatus to cause the deenergization of said relays but maintaining such change in electrical condition of such portion of said circuit, a subsequent operation of said switching contact causing the reenergization of 70 said relays to control the restoration of said trunk switch.

4. In a telephone exchange system, the combination with a plurality of automatic selector switches, of a test conductor extending therebetween, means actuated by a switch through the test conductor when a station is taken for use for first reducing the potential existing on the said test conductor and subsequently opening the test circuit, and means associated with one of 85 said automatic selector switches for determining such reduced potential or the absence of potential when such automatic selector switch makes contact with said test conductor.

5. In a telephone exchange system, the combination with an automatic trunk selector and an automatic line selector, of a test 95 circuit established in an operated position of said trunk selector including a test brush of said trunk selector and a test conductor of said line selector, a pair of relays at said trunk selector, one of said relays being included in said circuit and the other of said relays having two windings, its high resistance winding being normally in said circuit and its low resistance winding in a branch of said circuit closed by the energization of such double wound relay, a circuit breaking switch in said circuit at said line selector, and a source of current also in 100 said circuit.

In witness whereof, I hereunto subscribe 110 my name this 28th day of February A. D. 1911.

FRANK R. McBERTY.
